2,398,036

PRINTING MECHANISM

Robert E. Paris, Teaneck, N. J., assignor to International Business Machines Corporation, New York, N. Y., a corporation of New York

Application April 21, 1943, Serial No. 483,877

71 Claims.

(CL. 101—93)

This invention relates to a printing machine of the type which prints a plurality of characters at once, for example a complete line, or one or more parts of a line comprising a plurality of characters. One example of such a machine is the tabulating machine, but the invention is by no means limited to tabulating machines.

An important object of the invention is to increase the speed of operation. In the well known tabulating machines which have come into general use the printing mechanism comprises a separate type bar having all the characters, for each column of the record sheet. These type bars are moved longitudinally and stopped at the proper position to place the selected type member in printing position. After the impression is made the type bars are all returned to the normal position. A printing mechanism in accordance with the present invention increases the speed at which the impressions can be made by eliminating certain mechanical limitations of the earlier form of printing mechanism, avoiding the idle stroke of the type bars by which they are restored to the normal position, providing for the setting up and the printing to be carried out simultaneously by independent means, and reducing the movements of variably movable parts of the printing mechanism to very small limits.

Another object of the invention is to provide a printing mechanism having a more positive action than previously used printing mechanisms.

Another object is to provide a record controlled printing mechanism which will respond to records in which the characters are represented in accordance with predetermined different codes, without any change of setting of the machine, either manual or automatic.

Another object is to provide a printing mechanism having greater flexibility as to the number of different characters which can be printed by it. In the earlier tabulating machines mentioned above an increase of the number of type characters entails a reduction of speed of the machine, because of elongation of all the type bars. A printing mechanism in accordance with my invention is not materially affected in respect to speed, by a change in the number of characters which can be printed.

Another object of the invention is to provide a printing mechanism of the kind described, wherein the type characters can be changed by a simple manipulation.

Still another object is to provide a printing mechanism capable of printing the characters at

closer spacing than has been possible with the earlier tabulating machines.

Another object is to provide a printing mechanism of the kind described having fewer parts and a generally simpler construction.

Another object is to provide a multicolumn printer in which each type member serves a plurality of columns.

Another object is to provide a printing mechanism which prints without blurring, while the type members and paper have relative motion past the paper.

Another object is to provide a printing mechanism having a reciprocating type member carriage, which prints during the movement of the carriage in either direction.

Another object is to provide a printing mechanism having a reciprocating type member carriage, which prints without blurring, during the movement of the carriage in either direction.

Another object is to provide a printing mechanism which will produce a greater number of carbon copies than has been possible heretofore.

Another object is to provide a manifold printing mechanism in which the thickening of the paper pack incidental to increasing the number of sheets to be printed, automatically causes a proportionately greater impact of the type.

Still another object is to provide a printing mechanism which will print a large number of characters in one operation, with less shock than that which occurs in printing a similar number of characters on tabulating machines of the kind in use heretofore.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a front elevation of the machine, with the casing removed and parts broken away.

Fig. 2 is a right side elevation of the machine.

Fig. 3 is a right side elevation of the card reading mechanism.

Fig. 4 is a detail view of a portion of the ribbon guiding means.

Fig. 5 is a partly diagrammatic plan view of the machine.

Fig. 6 is a vertical section on the line 6—6 of Fig. 1.

Fig. 7 is an enlarged side elevation of one unit of the hammer and latching mechanism, in the normal position.

Fig. 8 is a similar view of the same mechanism, at the limit of the hammer cocking movement.

Fig. 9 is a section on the line 9—9 of Fig. 6.

Figs. 10, 11, and 12 are detail sectional views of three bearings in the hammer and latching bar mechanism.

Fig. 13 is an enlarged plan view, with parts in section, of a portion of the type member carriage and adjacent parts.

Fig. 14 is a plan sectional view on a large scale on the line 14—14 of Fig. 6.

Figs. 15, 16, and 17 are vertical sectional views illustrating three different positions of the storage mechanism and setting mechanism, in relation to one of the units of the selective printing control mechanism.

Figs. 18, 19, and 20 are three diagrammatic views illustrating the operation of the selective printing control mechanism.

Figs. 21 and 22 are perspective views showing two different positions of a unit of the storage mechanism, in relation to its related group of pins in the selective printing control mechanism.

Figs. 23 and 24 are diagrammatic plan views illustrating the relative positions of the type members and their actuating hammers, at the time the latter are released.

Fig. 25 is a vertical section on the line 25—25 of Fig. 1.

Fig. 26 is a plan view of the reciprocating drive of the permutation bar unit.

Fig. 27 is a section on the line 27—27 of Fig. 26.

Fig. 28 is a development of the spiral cams of the reciprocating drive.

Fig. 29 is an enlarged detail plan view, partly in section of a portion of the setting mechanism and cooperating parts of the storage mechanism.

Fig. 30 is a timing diagram of the setting mechanism.

Fig. 31 is a front elevation of the permutation bar unit and adjacent parts of the machine.

Fig. 32 is an enlarged front elevation of a portion of the permutation bar unit.

Fig. 33 is a detail cross section on a still larger scale of a portion of the permutation bar unit.

Fig. 34 is a diagram of one sequence of the controlling recesses of the permutation bars and corresponding settings of the selective control pins and two different codes for the control records.

Fig. 35 is a diagrammatic sectional view of one group of six permutation bars, showing the control recesses for the character "9."

Fig. 36 is a simplified circuit diagram.

Fig. 37 is a timing diagram, and

Figs. 38 and 39 are views showing portions of two control cards, with the same data represented in 12 point and 6 point code, respectively.

I have chosen to illustrate the invention as embodied in a record controlled machine, where its high speed can be fully utilized. The machine shown in the drawings is a tabulating machine, similar in its general arrangement to the one shown in the Peirce Patent No. 2,042,324. A tabulating machine of this kind comprises a card reading mechanism, an accumulating mechanism, and a printing mechanism. The accumulating mechanism has been omitted from the present disclosure, which is confined to the novel printing mechanism and the card reading mechanism which controls it.

A description of the major instrumentalities of the machine will be given first, followed by an

explanation of its operation and various details of construction.

Main drive

Upon the bottom side of a base 10 (Fig. 1) is mounted a part of the driving mechanism which operates continuously. This includes a belt and pulley connection 13 between a motor (not shown) and a worm shaft 14. The worm 15 thereon drives worm wheel 16 fixed upon shaft 17, so that said shaft continues running as long as the motor receives current.

At the right end of shaft 17 is a clutch for driving the printing mechanism. This clutch comprises a notched disk 18 (Fig. 2) fixed to shaft 17 and adapted to be engaged by a dog 19 pivotally mounted upon an arm 20 fixed to a gear 21. The gear 21 is carried by a stud shaft 22 in axial alignment with shaft 17 and, through idler gear 23, drives gear 24 mounted on shaft 25. An armature latch 26 pivoted at 27 upon an arm 28 and biased to the right by a spring 29, normally holds dog 19 out of engagement with the driving disk 18, in the position shown in Fig. 2. A magnet 30, upon energization, draws armature latch 26 to the left as viewed in this figure, releasing dog 19 so that its spring 31 may bring it into engagement with driving disk 18.

Upon deenergization of magnet 30 armature 26 will be moved by its spring into the path of a projecting toe of dog 19 to throw the dog out of engagement with disk 18. Arm 20 will be similarly engaged by armature 26 to prevent further movement of gear 21 in a clockwise direction. Arm 28 is pivoted near its mid point and provided at one end with a stout spring 32 to absorb the shock of stopping gear 21. The usual rebound latch 33 is also provided.

At its left end in Fig. 1 the shaft 25 has fixed to it a gear 34 which meshes with a gear 35 fixed to a shaft 36. At the left end of the latter shaft is fixed a gear 37 meshing with a gear 38 secured to a shaft 39. The parts of the printing mechanism which take their drive from the latter shaft will be described in due time.

In Fig. 3 shaft 17 is shown as carrying a second clutch driving disk 40 cooperating with a dog 41 mounted upon an arm 42 to which is fixedly connected a gear 43 to drive the card reading device, through an idler gear 44. The engagement of these clutch elements is controlled by a magnet 45 and armature latch 46 in the manner described in connection with magnet 30 and its armature latch 26.

The printing mechanism

The printing mechanism is mounted upon side frames 50 and 51, in an upper frame comprising side plates 52 and 53 attached by cleats 54 to subframe members 55 secured to the top of the side frames 50 and 51. The usual rotary platen 56 is mounted near the rear of the upper frame. Paper line spacing mechanism is provided therefor as described in the above-mentioned Peirce Patent No. 2,042,324 and the description will not be repeated in the present disclosure, since it forms no part of the invention. Figure 2 shows a shaft 57 which operates the pawl and ratchet mechanism (not shown) of the line spacing device, this shaft having fixed to it an arm 58 carrying a rod 59 cooperating with the fork of a lever 60 mounted on a stud shaft 61. To the latter shaft is secured an arm 62 connected by a link 63 to an arm 64 fixed on shaft 65. This shaft, which is the same as shaft 17 of Peirce

Patent No. 2,042,324, is rocked by a cam mechanism shown in Fig. 15 of said patent.

A printing ribbon 49 is supported and fed by mechanism of conventional form, including a spool 66 removably mounted upon a spindle 67, the bottom end of which has fixed to it a bevel gear 68. For movement of the ribbon in one direction, this bevel gear is in mesh with a bevel gear 69 on an axially shiftable shaft 70, which is intermittently rotated by the usual pawl and ratchet mechanism, not shown in the drawings. For movement in the opposite direction the shaft 70 is shifted to engage a bevel gear on its opposite end with a bevel gear on the spindle of the other spool not shown. The ribbon is drawn through tensioning rollers 71 past a guide member 72 adapted to be engaged by a clip near the end of the ribbon, to reverse the feed by shifting the shaft 70. The ribbon is further guided through a slot 73 (Fig. 4) in the bottom of an upright strip 74 secured to the frame in front of the platen, then back through a 45° slot 75, to pass across the front of the platen.

The pawl and ratchet mechanism (not shown) for intermittently rotating the shaft 70 is actuated by a shaft 76, which has fixed on its end an arm 77 connected by a link 78 to an arm 79 fixed upon a shaft 80. The shaft 80 is rocked by cams (not shown) on the shaft 25, through operating arms similar to those which rock the shaft 129 shown in Fig. 3 of the said Pierce Patent No. 2,042,324. The only difference is that in the present case the cams are shaped to rock the shaft 80 first clockwise, then counterclockwise.

Type member carriage

In front of the platen and ribbon is a type member carriage 81 (Figs. 2, 5, 6, and 13) mounted to travel parallel to the platen. This carriage comprises a square tube 82, to the bottom of which is fixed a rabbeted slide 83 guided in a groove formed by rabbeted plates 84 attached to the bottom of a stationary trough 85. Secured to the top of the square tube 82 is a channel shaped type member holder 86, the front wall 87 and rear wall 88 of which are slotted to form individual bearings for a row of type members 90. The type members are pulled to home position against an abutment bar 92 (see also Fig. 7) by individual retracting springs 91. Each type member is composed of a shank 93, which guides the type member in rectilinear motion normal to the platen axis, and a head portion 94 pivoted to the shank by a pin 95 and bearing a type 96. The type is made to strike the record sheet on the platen while the type carriage is in motion, the head 94 turning on the pin 95 during the brief period of impact, to avoid blurring of the impression. In the position of rest of the type member the sides of the head 94 fit snugly in the slot of the rear wall 88, but when the type member moves rearward toward the platen the tapered sides 90a of the head give it freedom to turn on its pivot in either direction, depending upon the direction in which the type member carriage is traveling at the time. The head is returned to the normal position after its impact with the platen, by the pull of the spring 91 and the camming action of the sides of the slot in the rear wall 88 against the tapered sides 90a of the type member head. This insures that the head always starts toward the platen in the normal position and there is no force tending to deflect it, until it strikes the platen—a feature important to uniform spacing. The adjacent surfaces on

5 the head and shank at 97 and 98 are arcuate, with the axis of the pin 95 as their center (see Fig. 13). The pin 95 has a loose fit in the hole in the two parts of the shank through which it passes, to allow the surface at 97 and 98 to abut and take up the forces transmitted by the impact of the printing hammer, to be described presently, against the type member. The shank of the type member and the edge of the abutment bar 92 have complementary V-shaped surfaces 99, to prevent rebound of the type member on its return to home position, thus preventing shadow impressions and insuring repeat operations when required, as will be seen later.

Printing actuator mechanism

For each column or character space of the record sheet, there is provided a printing actuator, in the form of a hammer 100 (Figs. 5, 6, 7, and 8). The hammers 100 are slidably mounted in bearing blocks 101 and 102, for rectilinear movement toward the type members. Each has associated with it a three armed impelling lever 103, these levers being rockably mounted on a stationary shaft 104. The downwardly extending arm 105 engages a shoulder 106 of the hammer; the upwardly extending arm 107 is connected by a link 108 to a driving spring 109 anchored by an adjustable hook 110 to one or another of two cross bars 111. The links 108, springs 109 and hooks 110 pertaining to the successive actuating levers down the line slope alternately upward and downward from their pivotal connection at 112 to the arms 107, to enable the space between them to be reduced. The levers 103 have a third arm 113 extending approximately horizontally, in position to strike a cushioned abutment 114, to limit the impelling movement of the levers.

Above the set of printing hammers is a retracting shaft 120 (Fig. 7) having a flange 121 adapted to engage a shoulder 122 on each of the hammers. The retracting shaft is rocked during a certain part of the machine cycle, from the position shown in Fig. 7 to a limit position shown in Fig. 8, to retract all of the printing hammers and place them in a position in which they can be latched by respective latching dogs 123 or 124 (see also Fig. 6). The latching dogs are in two groups rockably mounted on shafts 125 and 126, respectively, the dogs 123 on shaft 125 alternating with the dogs 124 on shaft 126. Each printing hammer has on its bottom edge a pair of recesses 127, into one or the other of which the related dog 123 or 124 can rise, when the hammer is retracted, to be in a position to engage the shoulder 128, when the shaft 120 starts back from its limit position. The hammers are made with two recesses 127 to avoid the need for two different parts, to coact with the differently positioned dogs 123 and 124.

While all the hammers are retracted by the shaft 120 during each machine cycle, only those pertaining to columns in which a character is to be printed in the particular machine cycle are latched in cocked position, the others being allowed to return to the position of rest shown in Fig. 7. For the purpose of controlling the latching of particular hammers, there is provided below each hammer 100 a latching bar 130 or 130a. The latching bars are slidably mounted in bearing blocks 131 and 132. Fig. 6 shows a latching bar 130 in front and a latching bar 130a behind, while Figs. 7 and 8 show only a latching bar 130a. These latching bars are identical in function, but have slight differences in shape, due to the fact

that the latching bars 130 cooperate with latching dogs 123 and with operating mechanism at their left ends, while latching bars 130a cooperate with latching dogs 124 and with operating mechanism at their right ends. The two kinds of latching bars are, of course, arranged alternately in the series. Each latching dog 123 or 124 has a leaf spring 133 held in a slot on its upper side and curving downward into a notch 134 on the upper edge of a related latching bar 130 or 130a. 10 The springs 133 are broad enough to extend across a pair of neighboring latching bars 130 and 130a, but each cooperates with only one latching bar, the other latching bar having an enlarged recess 135 which allows the latching bar to move to its 15 limit positions in both directions without touching the spring pertaining to the neighboring latching bar. On the latching bars 130a the active notch 134 is at the right and the inactive recess 135 at the left (Fig. 7) while on the latching bars 130 the position of the active notch and the inactive recess is reversed (Fig. 6). Each latching bar 130a has associated with its right end an operating lever 136, which is pivoted on a rod 137 above the latching bar and limited in its swing to the right by a rod 138. Each latching bar 130 has a downwardly extending lug 139 engaged by the top of an operating lever 140, which is pivoted on a rod 141 below the latching bar and limited in its clockwise rotation by a rod 142. The operating levers 136 are rocked clockwise to shift their related latching bars to the left, while the operating levers 140 are rocked counterclockwise, to shift their related latching bars to the left also. The latching bars can themselves be latched in their left limit position by spring detents 143 which engage shoulders 144 on the related latching bars. The latching bars are unlatched from their detents and returned to the right, by a knock-off plate 145 fixed to a rock shaft 146. The shaft 146 has fixed to it an arm 147 connected by a link 148 to an arm 149 (Fig. 25) on the retracting shaft 120. Thus, when the retracting shaft is rocked clockwise to retract the hammers, the knock-off plate 145 is swung out to the position shown in Fig. 8. On its return movement, executed in unison with the retracting shaft, the lower edge of the knock-off plate first strikes an inclined portion 143a of the spring detents, disengaging them, then strikes the ends of the latching bars and throws them to the right (see Fig. 6). The latching bars are caught by their detents 143 each time they are moved to the left and are not released until a later time in the cycle, just as the printing portion of the cycle begins. Before the leftward movement of the latching bar begins, the latching dogs 123 and 124 stand in the position in which the dog 124 is shown in Fig. 7, their springs engaging the shoulders 150. The movement of the latching bars to the left acts through the springs 133 to throw the dogs against the bottom edge of the printing hammers, so that when the latter approach the limit of their leftward movement, the dogs rise into notches 127 in position to engage the shoulders 128 when the 60 retracting shaft 120 rocks in the reverse direction. When the latching bars have been restored to normal position (Fig. 6) the latching dogs which have been set by them are held by toggle action against the shoulders 128 of the hammers.

Storage mechanism

In accordance with a feature of the present invention, the printing of one line, or group of characters, is to occur during the same machine cycle

with the reading of the record card, or corresponding unit of a control record, which is to control the printing of the next line, or group of characters. For this reason, the data sensed from a subsequent record card is stored in a storage mechanism and transferred to a selective printing control mechanism during the interval between successive printing operations. The storage mechanism has the additional function of selectively actuating those operating levers 136 and 140 pertaining to columns in which characters are to be printed, to latch the related hammers in cocked position. In describing the storage mechanism reference will be made particularly to Figs. 6, 15, 16, 17, 21, 22, and 25.

For each column of the record sheet, there is provided a storage unit comprising six settable plates 160, individually identified by subscripts 1, 2, 3, 4, 5, and 6 (Fig. 21). The storage units are mounted in two rockable frames 161 and 162 (Figs. 6 and 25) respectively pivoted at 163 and 164 on the side plates 52 and 53. Each of the frames 161 and 162 is constructed of side bars 165, a bottom cross bar 166, and a top cross bar 167. The storage plates of each storage unit are separated from each other by spacing plates 168 (not shown in Figs. 21 and 22, but see Fig. 29), so that movement of any one will not affect the position of any other plate. The upper end of each storage unit comprising six settable plates 160 and five spacing plates 168 is freely held in an individual slot of a comb 169 secured to the top bar 168. At their lower ends the storage plates and spacing plates are slotted to embrace a cross pin 171 of a stirrup 170 pivotally mounted on a stud 172 attached by a screw 173 to the bottom cross bar 166 of the rocking frame. Laterally projecting toes 193 of the storage plates and 194 of the spacing plates (see Fig. 16) normally rest upon a cushion stop 195 on the bottom bar 166. The storage plates can move upward individually until their lugs 174 strike a cushion stop 175 on the upper cross bar 167. The spacing plates are held against upward movement by their lugs 176 constantly bearing against this cushion stop.

The storage plates 160 of each storage unit pertaining to a column in which a character is to be printed are set up singly, or in various combinations, by a setting mechanism to be described, to represent different characters in accordance with a code. In the unset position, shown in Figs. 6 and 15, the tops of the storage plates are below the ends of the operating levers 136 or 140. In the set position, shown by the plate 160-1 and 160-4 in Figs. 16 and 22, the top of the storage plate stands in position to actuate the operating lever 136 or 140 when the rocking frames are rocked inward. Only one storage plate, 160-5, is too short (see Figs. 15 and 21) to reach the bottom of the operating lever, even when set up. Thus the setting up of any storage plate in a particular storage unit (with the exception of a single setting of the plate 160-5) will result in the latching of the related hammer 100 in cocked position, when the frames 161 and 162 are rocked in, as shown in Fig. 17.

Drive for rocking the storage, hammer retracting, and latch bar releasing mechanisms

The tops of the side bars 165 visible in Fig. 25 are connected by links 177 and 178 to pivot pins 179 and 180 on the plate 149. At the opposite ends of the frames 161 and 162 the tops of the side bars 165 (see Figs. 1 and 5) are similarly connected to a plate 149a fixed to the shaft 120 near

its opposite end. The retracting shaft 120 has fixed to its left end (Figs. 1 and 5) an arm 181 pivotally connected by a pin 182 (Fig. 25) to a pitman 183. The lower end of the pitman has a slot 184 by which it is guided upon an oval bearing member 185. Fixed to the gear 38, which makes one revolution per machine cycle, is a double cam comprising complementary cam disks 186 and 187, upon which bear, respectively, rollers 188 and 189 carried by pins 190 and 191 on the pitman. The pitman is spaced from the side frame 51 and cam disk 187 by washers 192. During a certain portion of the machine cycle the cam 186, 187 throws the pitman downward, then upward, rocking the retracting shaft 120 and the storage and latch bar releasing mechanisms operated thereby, in the manner described.

Card reading mechanism

In the illustrative embodiment the setting of the storage mechanism is controlled by a card reading mechanism, shown in Fig. 3. By this mechanism, which is in general similar to that disclosed in the Peirce Patent 2,042,324, the record cards are fed singly from the supply magazine 200 by the usual card picker mechanism comprising a slidably mounted reciprocal plate 201 carrying a picker knife 202 for cooperation with the record cards. The plate 201 has a pin and slot connection 203 with an arm 204 of a bell crank lever, the other arm 204a of which is connected by a link 205 to a stud 206 mounted eccentrically on a gear 207 meshing with a ring gear 208. The ring gear is driven as long as the card feed clutch dog 41 is engaged with the notch of the driving disk 40, through an idler gear 209 meshing with the gear 44 and with the ring gear 208. The plate 201 is reciprocated by the crank pin 206 and upon each reciprocation the picker knife 202 feeds a card from the magazine to a first pair of feed rollers 210 driven by gears 211 from the ring gear 208. The rollers 210 feed the card between the upper analyzing brushes 212 and a contact roller 213, thence to a second pair of feed rollers 214 driven from the ring gear 208 by gears 215. A third pair of feed rollers 216 driven from the ring gear 208 by gears 217, feeds the card between the lower analyzing brushes 218 and a contact roller 219. On their passage into the feed rollers 216 the cards depress a card lever 220 operating a pair of contacts LCL through a linkage 222. Below the lower brushes 218 the card is received by feed rollers 223 driven from the ring gear 208 by gears 224. The card passes through successive pairs of feed rollers 225 and 226 to a rotary stacker 227 driven by its gear 228 through a gear 229 on the gear 207. The stacker delivers the card to a discharge stack 230.

A cam shaft 231 driven from the ring gear 208 through idler gears 232 and 233 and a gear 234 fixed to shaft 231, carries two cams, one of which appears at 235, which respectively operate two similar pairs of contacts CF1 and CF1, the function of which will be mentioned later.

The cards may be, for example, twelve point cards punched in alphabet code, as shown in Fig. 38, or cards of the same size punched in a six point code, as shown in Fig. 39. These cards are fed by the card feeding mechanism so that the successive index point positions pass under the upper and lower reading brushes at certain differential times in the machine cycle, the 9 index point position reaching the brushes first. Each set of brushes comprises an individual insulated brush for each column.

Setting mechanism

For each unit of the storage mechanism, that is to say, for each column of the record sheet, there is a two-coil magnet 240 (Fig. 6). These magnets are electrically connected to individual brushes of the lower set of reading brushes 218 and are energized at the differential times when their respective brushes sense perforations in the card. Each magnet has an armature latch 241, biased away from the magnet by a spring 242, to engage the foot of the related stirrup 170. The magnets pertaining to the rear storage mechanism are arranged in groups of three, as shown at the right in Fig. 6, the group being repeated for each three storage units. The same arrangement of the magnets pertaining to the front storage mechanism is indicated at the left in Fig. 6. The magnets are mounted on bars 243 of insulating material.

- 20 The setting mechanism comprises two rotary setting units 245 and 246, for the rear and front storage mechanisms, respectively. Each setting unit has a central shaft 247 journaled in bearings 248 on the side plates 52 and 53 (Fig. 1).
 25 The shafts are extended to the right in Fig. 1, to mount gears 249, each of which is held against movement axially of the shaft by a collar 251 and the hub of an arm 250, both held to the shaft by set screws. The angular position of the gear in relation to the shaft is adjustably fixed by a connection between the gear and the arm 250. The latter is forked at its end and receives between the two prongs 252 of its fork (see Figs. 2 and 5) a stud 253 on the gear 249. The stud 30 is set to an exact position between the prongs of the fork by set screws 254. The gears 249 mesh, respectively, with two gears 255 and 256, the latter meshing with a gear 257 pinned to shaft 39. The gears 255 and 256 are fixed upon individual shafts 258 and 259 (Fig. 26) the journaling of which will be described in more detail later. These two shafts are interconnected to rotate in opposite directions, by a pair of gears 260 and 261. Through this gearing, and the main drive 45 earlier described, the setting units 245 and 246 are driven constantly in clockwise and counterclockwise direction, respectively, whenever the print clutch magnet 30 is energized. Their rate of movement is one revolution per machine cycle.
 50 The setting units 245 and 246 are alike, except for a certain difference, to be mentioned, due to their opposite directions of rotation. Their construction will be described with particular reference to the setting unit 245. As shown 55 particularly in Fig. 29, the shaft 247 has mounted upon it groups of toothed disks 270. There are six disks in each group, individually identified by the numbers 1, 2, 3, 4, 5, and 6, and they are separated from each other by thin separating 60 disks 271 of larger diameter. Each group is spaced from its neighboring groups by thick spacing disks 272 of the same diameter as the disks 271. All of the disks are keyed to the shaft 247 by a key 273 and are held in a fixed 65 axial position between two collars 274 secured by screws. The disks 270 have teeth 270a, in positions shown in Fig. 30. The positions refer to degrees of the machine cycle at which the teeth 270a strike the toes 193. In Figs. 6 and 15 70 to 17 the teeth of disk 270-1 are shown in full lines and those of disk 270-2 in dotted lines.
 There is a group of six setting disks 270 for each unit of the storage mechanism. These storage units, it will be recalled, each comprise 75 six storage plates 160 supported by a common

stirrup 170. Each storage plate in a group is in the same plane with a related setting disk 270 and its toe 193 is inserted into the annular space surrounding said disk 270, which is laterally bounded by two separating disks 271, or a separating disk and a spacing disk 272. In all of the possible positions of the storage plates their toes 193 remain within the outer circle of the disks 271 and 272 and are thus secured against lateral displacement which might result in contact with the wrong setting disk. In the normal, latched position of the stirrup 170 (Fig. 6) the toes 193 of the appurtenant storage plates do not reach to the circle in which the extremities of the teeth 270a of the setting disks travel. When the related magnet 240 is energized, releasing the bottom of the stirrup 170, the bottom end of the individual group of storage plates 160 is rocked out, by an individual leaf spring 276 mounted on a bar 243, until it strikes the side face of the cushion stop 195 (compare Figs. 6 and 15). The toes 193 of one or more of the storage plates will find a tooth 270a just coming up and such storage plates will be raised to the position of 160—1 in Fig. 16. The slots 196 of the storage plates have a hump 198 which, during the upward movement of the storage plate, cams the cross pin 171 to the left in Figs. 15 and 16, to restore the stirrup to the vertical position, in which it is relatched by the armature latch 241 (Fig. 16). The leftward movement of the cross pin 171 returns to normal position those storage plates which have not been raised. A knock-off tongue 244 on the armature latch is engaged by the bottom of the stirrup, to free the armature from the magnet, if necessary. Any storage plate set to the upper position is retained by engagement of the spring 276 under its lug 197.

By comparing the timing diagram of the teeth of the setting disks 270, Fig. 30, with the main timing diagram, Fig. 37 it will be seen that the energization of the magnet 240, which occurs at about the time the leading edge of a perforation 9, 8, 7, etc., reaches the reading brush, is well ahead of the arrival of the corresponding teeth of the setting disks at the striking position. For instance, the energizing impulse for the 5 index point starts at 81° and the teeth at the 5 index point position on setting disks 2 and 3 reach the striking position at 90°. The difference of 9° is ample for the energization of the magnet and movement of the storage plates into active position in advance of the teeth.

The magnet of a particular storage unit may be energized one or more times during a single machine cycle. Depending upon the differential times at which it is energized, a particular storage plate, or combination of storage plates 160 will be set up. Thus, if a single hole is sensed at the 9 index point position the 1 and 2 storage plates will be set up. If a second hole is sensed at the X position the 5 and 6 storage plates will also be set up, so that at the end of the sensing portion of the cycle the 1, 2, 5, and 6 storage plates will be set up. If a single hole is sensed at the 4 position the 3 storage plate will be set up alone. The various single and combinational settings which can be made can be comprehended by examination of Fig. 30. The different settings can be made to represent different characters, for the selective control of the printing mechanism, according to any chosen code, as will be illustrated presently.

The setting unit 246 differs from the setting

unit 245 only in the order of the teeth on its setting disks 270, which is reversed, because the setting unit 246 rotates in the opposite direction.

Permutation bar unit

The manner in which the printing hammers 100 pertaining to columns in which a character is to be printed are latched in cocked position has been explained. The mechanism whereby the 10 printing hammers are selectively released, as the type carriage moves past them, so as to strike particular type members, will now be described.

Extending through the middle of the machine is a long permutation bar unit 300, shown in side elevation in Fig. 31 and in cross section in Fig. 6. The permutation bar unit is made up of a central vertical plate 301 upon each of the opposite sides of which are riveted six permutation bars 302 and one additional cam bar 303. The 20 permutation bars 302 are individually identified, beginning at the bottom, with the numbers 1, 2, 3, 4, 5, and 6. The permutation bar unit extends through oblong openings 304 and 305 in the side plates 52 and 53 (see also Fig. 25). At the top and bottom of these openings are mounted roller bearings 306 and 307, which guide the permutation bar unit for vertical and lateral reciprocating movement. The roller bearings are mounted in bearing blocks 308a, 308b, 308c, and 308d (Fig. 30 2), the inner faces 309 (Fig. 31) of which guide the permutation bar unit, by the lateral edges 310 (Fig. 33) of the permutation bars 302 and the cam bar 303. The top edges of the central plate 301 and the upper permutation bars 302—6, which 35 constitute the top edge of the permutation bar unit, and the bottom edges of the central plate and the cam bars 303, which constitute the bottom edge of the permutation bar unit, are shaped to form complementary cam surfaces coating 40 with the rollers 306 and 307, to impart vertical movements to the permutation bar unit in certain portions of its stroke. Fig. 31 shows the permutation bar unit at the extreme left end of its stroke and held by the flat surfaces 313 at the 45 upper limit of its vertical movement. Immediately after it begins to move to the right the sloping portions 315 of the cam edges ride over the roller bearings and let the permutation bar unit down to the lower limit of its vertical movement, where it remains through most of the stroke, as the flat portions 316 of the cam edges ride on the roller bearings. As it approaches the right end of its stroke the sloping portions 317 of the cam edges ride up on the roller bearings 50 and lift it to the upper limit of its vertical movement. At the reversal of the stroke the flat portions 318 of the cam edges rest against the roller bearings. The four bearing blocks 308a-d are secured to the side plates 52 and 53 by screws 111. 55 The position of the bottom pair of blocks is permanently fixed, but the upper pair can be adjusted slightly in a vertical direction by loosening their screws 111, which are somewhat smaller in diameter than the holes in the blocks through 60 which they pass, and adjusting the tie bolts 112. 65

Reciprocating drive of the permutation bar unit

The mechanism for reciprocating the permutation bar unit is mounted upon a vertical support comprising two plates 320 and 321 (Figs. 1, 26, and 27) secured by screws 322 to the side frame 50. The plate 321 has screwed into it, and rigidly extending from it, two stationary round bars 323 and 324, the reduced outer ends 70 of which pass through holes in an outer plate 325

and are threaded to receive clamping nuts 326. The outer plate, the round bars, and the vertical supporting plates are thereby united into a rigid frame. The two shafts 258 and 259 are journaled in bearings 327 and 328 in the plates 320, 321 and 325. These shafts, as previously mentioned, are geared to rotate in opposite directions by intermeshing gears 260 and 261 fixed to them, and take their drive through gear 256 fixed to shaft 259, which meshes with the gear 257. The shaft 258 rotates clockwise and the shaft 259 counterclockwise. The shafts 258 and 259 have rigidly mounted upon them cam cylinders 330 and 331, respectively. For constructional reasons each cam cylinder is built up of three parts, namely, two hub members 332 and 333, fixed to the shaft by pins (not shown), and a central shell 334, attached to the hubs by pins such as 335. The cylinders 330 and 331 have machined on to their surfaces two spiral cam grooves 336 and 337, which are identical in shape, but are relatively reversed in position, so that the outer end of the cam 336 is like the inner end of the cam 337. The end thrust of the spiral cams is taken by inner ball bearings 338 and outer ball bearings 339. A traveler 340 is rockably and slidably mounted upon the round bar 323 and has mounted upon two oppositely extending arms 341 a pair of follower rollers 342 and 343, which can be engaged alternatively with the respective cams 336 and 337. When the follower 342 is engaged with the cam 336 the traveler moves inward, whereas when the follower 343 is engaged with the cam 337 the traveler moves outward. At the inner end of the traveler, there is a hub 344 having a radial aperture 345 through which extends a foot 346 (Fig. 31) depending from the permutation bar unit 300. The foot 346 is part of a bar 347 (Fig. 2) which, with a matching bar 348, is clamped by bolts 349 to the end of the central plate 301 of the permutation bar unit. The foot 346 extends through the aperture 345 into a longitudinal groove 350 in the round bar 323. The aperture is shaped to permit relative rocking movement of the traveler hub with respect to the foot 346, while retaining a fixed relation thereto into the direction of the stroke of the traveler. The groove 350 steadies the foot 346 laterally. Above and to the rear of the round bar 323 is a stationary square bar 351, fixed to the inner plate 321 and outer plate 325 by screws 352. Upon one side of this square bar is fixedly attached a plate 353, the lower edge of which is positioned for cooperation with a pin 354 extending at an angle upward from the traveler 340. The length of the plate 353 is such that the pin 354 can rock past its ends at the two limit positions of the traveler, but in all intermediate positions will be held on one side of the plate or the other, for the full extent of movement of the traveler. The rocking of the traveler in the limit positions is accomplished by reciprocal inclined surfaces in the bottom of the cam grooves 336 and 337, indicated by dash lines 355 and 356, in Fig. 27. This view is taken at the time when the traveler has completed its inward movement and is about to be rocked to move the follower 342 out of the cam 336. A clockwise angular movement of the cam roller 331 through 180° from the position shown will cause the cam surface 355 to raise the follower 342 to the top of the cam channel 336, while a synchronized counterclockwise movement of the cam 336 will allow the cam follower 343 to ride into the bottom of

the cam channel 337. A similar, but reversed, co-action occurs when the traveler reaches the outer limit of its stroke.

Figure 28 is a developed diagram of the cam grooves 336 and 337. The cams move in opposite directions, as indicated by the arrows C1 and C2. The direction of movement of the traveler 340 (Fig. 26) while the follower 342 is in the cam groove 336 is indicated by the arrow T1; the direction of movement of the traveler while the follower 343 is in the cam groove 337 is indicated by the arrow T2. The explanation of the diagram will start with the follower 342 at 330° (342a) on the cam groove 336, which is its position of rest when the type carriage stops near the left end of its travel. The traveler is accelerated to its high speed as the follower 342 moves along the cam groove 336 from 330° to 360° (342b) which is 0° of the next machine cycle. From 0° to 234° (342c), the traveler executes a movement of uniform high speed in the direction of the arrow T1. Between 234° and 250° (242d) the traveler decelerates to a stop. At 250° the follower 343 is over the entrance of cam groove 337 (at 343d) and the traveler begins to rock. From 250° to 324° (342e, 343e), as the cam grooves 336 and 337 move synchronously to the left end to the right, respectively, the traveler executes a movement of uniform reduced speed in the reverse direction (arrow T2), being moved by both cams, which have the same uniform pitch and direction. At 324° the cam groove 336 terminates. From 324° to 360° (343f) the follower 343 moves along the cam groove 337 and the speed of the traveler is accelerated in the direction of the arrow T2. At 360°, which is also 0° of the next cycle, the traveler begins its uniform high speed movement in the direction of the arrow T1, which continues to 234° (343g). From 234° to 250° (343h) the traveler is decelerated to a stop. At this point the traveler begins to rock as the follower 342 enters the cam groove 336 again (342h). From 250° to 324° (343i, 342i) the traveler moves in the direction T1 at uniform reduced speed, as it rocks to move the follower 343 out of cam groove 337 and the follower 342 into the cam groove 336. From 324° to 360° (342b) the traveler is accelerated to full speed in the direction of T1.

Summarizing the movements imparted to the traveler by the spiral cam grooves in one machine cycle, the traveler first executes a movement in one direction at a uniform high speed, for 234° of the cycle, then decelerates to a stop, reverses its direction of movement, and accelerates to the same high speed in the opposite direction. In the next cycle the sequence is identical but the directions of movement in the corresponding parts of the sequence is reversed. The printing and the setting of the storage mechanism take place in the part of each cycle during which the traveler is moving at the uniform high speed. The transfer of settings from the storage mechanism to the selective printing control mechanism, and the cocking of the printing hammers, are carried out during the remaining 126° of the cycle.

Type carriage drive

The type carriage reciprocates with the permutation bar unit and for this purpose is directly connected thereto. The connection has a small amount of lost motion at the reversal of the stroke, for a reason to be explained later. Clamped to the top of the right end of the per-

mutation bar unit is an arm 360 (Figs. 2 and 5). A downwardly bent end 361 of the arm and a plate 362 are clamped to opposite sides of the permutation bar unit by bolts 363 (see also Fig. 31). The arm 360 has fixed to its rear end a plate 364, with upturned lugs 365 into which are threaded screw stops 366 and 367 with lock nuts 358. The right end (Figs. 5 and 31) of the square tube 82, which forms part of the type member carriage, overhangs the plate 364. In suitable holes in the top and bottom walls of the tube 82 is mounted a pin 370 having a flange 371 which rests upon the top of the tube 82 and is clamped thereto by a pivoted clip 372. The bottom end 373 of the pin 370 is square and stands between the ends of the stops 366 and 367. The stops are adjusted to insure an exact relative position between the permutation bar unit and the type member carriage, during the travel in each direction. The relative positions are different for the two directions of travel, as will be explained later, the shift from one to the other being permitted by the play between the bottom end 373 of the pin 370 and the stops 366 and 367.

Selective printing control mechanism

The permutation bars 302 on the front side of the central plate 301 (left side in Fig. 6) are similar to those on the rear side of the central plate, that is to say, they are a mirror image of the latter. Each permutation bar has a horizontally jutting ledge, the bottom face 380 of which has a particular arrangement of recesses and flat surfaces, which coat with other mechanism to be described, to control the selective operation of the type members. The recesses are arranged in two strips on opposite sides of the longitudinal median line of the bottom face of the ledge. The recesses in the outer strip, such as 381 in Fig. 33 will be referred to herein as clearance recesses, to distinguish them from the recesses in the inner strip, such as 382 in Fig. 33, which will be referred to as control recesses. Both, however, are effective to control the selective operation of the type members.

One arrangement of the recesses 381 and 382 is shown diagrammatically in Fig. 34. In the wide column with the title "Permutation bars," there is a diagram of one complete sequence of recesses of the front set of permutation bars 1, 2, 3, 4, 5, and 6, and at the bottom, after "1/8," the start of the next sequence. The diagram is divided by horizontal lines to indicate the individual zones of the set of permutation bars pertaining to each character. The characters to which the different horizontal zones pertain are indicated in a column entitled "Character." The horizontal zone lines in the diagram correspond to vertical zone lines 385 in Fig. 32. The portions of the six permutation bars within one vertical zone in Fig. 32 pertain to one character and present a distinct combination of clearance recesses and control recesses. By way of example, the character "1" has, in the No. 1 permutation bar a control recess 382. In the permutation bars 2 and 3 this zone has clearance recesses 381. In the No. 4 permutation bar, it has a control recess 382. In the 5 and 6 permutation bars, it has clearance recesses 381. The next zone, pertaining to the character A, differs from the previous one only in that No. 6 permutation bar has a control recess instead of a clearance recess. The recesses can be seen more easily on the diagram, Fig. 34. The clearance recesses are indicated by vertical shade lines in the right hand strip of

each permutation bar, while the control recesses are shown by horizontal shade lines in the left hand strip of each permutation bar. On following up or down the zones it will be observed that there is always at least one change from a clearance recess to a control recess, or vice versa, in at least one of the permutation bars, on passing from one zone to the next. Fig. 35 is a diagrammatical vertical section of the six permutation bars, shown side by side instead of in a vertical row, the section being taken in the middle of the zone pertaining to the character "9." The clearance recesses 381 and control recesses 382 can be checked with the zone partially shown just above, where the permutation bars are broken off at the middle of the zone pertaining to the character "9" in the second sequence.

It was stated that the different vertical zones of the permutation bars pertain to different characters. By this is meant that each zone maintains a definite position in relation to a particular type member, throughout the printing portion of one cycle. Thus, when a particular zone of the permutation bar reaches a correspondingly set selective control unit (to be described shortly) pertaining to a certain column, the type member related to that zone will be approaching printing relation to that column. Since there is a time lag between the detection of a particular zone of the permutation bars by a selective control unit and the resulting impact of the related type against the paper, provision is made, as previously described, for the type member carriage to shift its position, in relation to the permutation bar unit, as the latter reverses its direction of movement. This shift, which is accurately controlled by adjustment of the stop screws 366 and 367, positions the type member just far enough behind the related zones of the permutation bars to place the printed characters in the centers of the columns of the record sheet.

On the front and rear sides of the permutation bar unit (left and right sides, respectively, in Fig. 6) are two assemblies of selective control unit, each unit comprising six pins 390 in a vertical row, individually numbered from the bottom up as 1, 2, 3, 4, 5, and 6. These assemblies of pins are mounted in two frames, each comprising a top bolster 391, a foot plate 392, an outer side plate 393 and an inner side plate 394. The pins 390 fit freely into round holes in the outer plate 393 and into vertically elongated holes 395 in the inner plate 394. The pins have reduced necks 396 and heads 397 which coat with the bottom faces 380 of the ledges of the permutation bars. In the two assemblies of selective control devices, there are, altogether, as many units each comprising a vertical row of six pins, as there are printing hammers 400. Each vertical row of six pins has associated with it a yoke in the form of a small vertical strip 400. Each yoke has six holes 401 (Fig. 9), each large enough to permit the body of a pin to pass through it. The strips are held freely, by the lateral edges 310 of the permutation bars, in individual grooves in guide bars 402 (Fig. 33) secured by screws 412 upon the inner side plates 394. The bars 402 also serve to stabilize the permutation bar unit by bearing against the edges 310. The holes 401 of the yokes embrace the necks of the pins, permitting the latter a short setting movement inward toward the central plate of the permutation bar unit. The normal, unset position of the pin head in relation to the bottom face 380 of the

ledges of the permutation bars is indicated by full lines at 397a in Fig. 33, while the set position of the head is indicated by dot and dash lines at 397b. In the unset position, the heads coact with the clearance recesses 381, while in the set position they coact with the control recesses 382. Serpentine springs 403 weave alternately on opposite sides of the six pins constituting one unit and are held against the outer plate 393 by shoulders 404 of the top bolster 391 and foot plate 392, to hold the pins frictionally in their unset or set position during the printing portion of the machine cycle.

It was stated that there is one unit composed of a vertical group of six pins 390 for each printing hammer 100, each unit having an individual yoke 400. The units of the front assembly are staggered with respect to those of the rear assembly, as can be seen in Fig. 9 by the relative positions of the yokes 400R pertaining to the rear assembly and the yokes 400F pertaining to the front assembly (the latter are broken off and their lower outlines indicated by dot and dash lines). A coupling member 405 is pivotally connected at 406 to the top of each yoke 400. The top of each coupling member is provided with a hook 407 (Fig. 18) to coact with the shoulder 408 of the related hammer latching dog 123 or 124. The coupling members of the front yokes 400F coact with the dogs 123, while those of the rear yokes 400R coact with the dogs 124. Thus, the alternate arrangement of the yokes in the front and rear assemblies corresponds to the alternate arrangement of the latching dogs in the front and rear positions. The coupling members 405 are biased in clockwise direction (Fig. 6) by springs 409, which are connected to their arms 410 and anchored to combs 411 secured to the top bolsters 391. The coupling members extend through individual slots in these combs, for lateral stabilization. The springs 409 also constantly urge the yoke upward and hold the heads 397 of the pins against the bottom faces 380 of the ledges of the permutation bars. When the head of any one of the six pins pertaining to one yoke bears upon a flat portion of the permutation ledge with which it coacts, the hook of the related coupling member is held below the shoulder 408 of its latching dog 123 or 124, if the dog is in the latching position. This is the position shown in Fig. 6. When the heads of all six pins find recesses at the same time the yoke is permitted to rise a sufficient distance to engage the hook of its coupling member over the shoulder of the related latching dog. The arrangement of the recesses is such that for each setting of the pins, when all six pins of a group find a corresponding combination of recesses, permitting the group to rise, at least one pin of the group will immediately thereafter be engaged and cammed down by the end of the recess into which it has moved, thereby pulling down the yoke and releasing the latching dog from the printing hammer.

The operation of the selective control mechanism is shown in three semi-diagrammatic views, Figs. 18, 19, and 20. In these views, the set of permutation bars is moving to the right past a unit of the selective control mechanism comprising six pins 390 pertaining to a yoke 400. The zones of the permutation bars included in these views are shown by the characters 1/8, 0, J, etc., at the top of each view. The order of the characters indicates that this is the rear set of permutation bars, since in Fig. 34, which shows the order of the characters in the front set of per-

mutation bars, the order is reversed. The pins 390 are assumed to be set to print the character "1." Reference to the right-hand column in Fig. 34, entitled "Set pins" shows that the character "1" requires pins 1 and 4 to be set and the other four pins to be unset. Checking this with the column entitled "Permutation bars," it will be seen that permutation bars 1 and 4 have a control recess in the zone pertaining to the character "1" and permutation bars 2, 3, 5, and 6 have clearance recesses in this zone. In Figs. 18, 19, and 20 only the clearance recesses of the permutation bars 2, 3, 5, and 6 are shown and these bars appear in side elevation; while only the control recess of the bars 1 and 4 are shown and these bars are in section.

In Fig. 18, which shows the "S" zone of the permutation bars in register with the pins 390 of the selective control unit, the heads of the pins 2, 3, 4, and 6 are in position to drop into recesses, while the pins 1 and 5 rest against flat faces of their permutation bars and hold the yoke 400 down so that the hook 407 is below the shoulder 408 of the dog 124, which is latching the hammer 100. As the permutation bar unit moves to the right from the position of Fig. 18 into that of Fig. 19, the heads of pins 1 and 5 roll up into the recesses of their permutation bars in the zone relating to character "1," the heads of the other pins being still free to drop into recesses continuing from the previous zone. The yoke 400 rises in response to the pull of spring 409 and the hook 407 of the coupling member engages over the shoulder 408 of the latching dog 124. As the permutation bar unit moves further to the right, into the position shown in Fig. 20, the head of the No. 6 pin is cammed down by the end of the recess in the No. 6 permutation bar and pulls the yoke 400 down, releasing the latching dog and freeing the hammer 100. If the permutation bar unit had been moving in the opposite direction, the action would have been the same, except that the No. 6 pin would have ridden into the recess in the No. 6 permutation bar, to allow the hook 407 to engage, and the No. 1 and 5 pins would have been cammed out of their recesses to release the latching dog.

Restoring the selective control pins

The transfer of a new setting to the selective control pins is immediately preceded by a return of the pins set in the previous cycle to normal position. This function is performed by the permutation bar unit 300, as it moves upward near the end of its stroke in either direction. The first effect of this upward movement is to allow the yokes 400 to rise, under the force of springs 409, until the shoulders 405a of the coupling members 405 strike the combs 411. Further upward movement of the permutation bar unit clears the bottom faces of the ledges from the heads of the pins. Each of the cam bars 303 and each of the permutation bars 302—1 to 302—5 has an inclined cam face 430 (Fig. 33), which engages the head of a related pin 302 during the further upward movement of the permutation bar unit and restores the pin to normal position, if it had been previously set. Shown in the timing diagram, Fig. 37, by the curve entitled "Restore pins," the upward movement of the permutation bar unit, which results in the restoring of pins to their normal position, begins at 216° and ends at 252°. At the latter point in the machine cycle the pins therefore stand in normal position and clear of the ledges of the permutation bars.

Transfer of setting to the selective control units

The selective control pins 390 are set by transferring to them the settings of the storage mechanism. For each unit of the selective control mechanism comprising a vertical row of six pins 390 there is a corresponding unit of the storage mechanism, comprising six storage plates 160. The manner in which the storage plates receive combinational settings has been described previously. Each storage plate 160 has a bent-over finger 160a for cooperation with a related pin 390 of the corresponding unit of the selective control mechanism. The fingers 160a are individually numbered 1, 2, 3, 4, 5, and 6, indicating their relation to the selective control pins 1, 2, 3, 4, 5, and 6, respectively. In the normal, unset position of the storage plates (Figs. 15 and 21), the fingers 160a are out of alignment with the respective pins 390. The setting of a storage plate moves its finger into alignment with the corresponding pin 390, as illustrated in Figs. 16 and 22 by the fingers 160a—1 and 160a—4.

At about 252° in the machine cycle (see Fig. 37, the curve entitled "Rock storage plates") the frames of the storage mechanisms, 161 and 162, begin to rock inward. In this movement, the fingers 160a of any storage plates 160 which have been set in the previous setting operation will strike the related pins 390 (Fig. 17) and move them from position 397a (Fig. 33) to position 397b. The setting of the pins is completed by 300°, before the bottom faces of the ledges of the permutation bars have reengaged the heads of the pins, on the downward movement of the permutation bar unit. Thereafter the shaft 120 will rock counterclockwise and return the storage mechanism frames to their original position. During this return movement of the storage mechanism frames, a pair of restoring vanes 420R and 420F fixed in shafts 421R and 421F, respectively, which are rotating in the direction of the arrows 422R and 422F, engage shoulders 423 on any storage plates in the upper, set position and push them down to the normal, unset position. The shafts 421R and 421F are rotated once in each machine cycle by gears 424R and 424F fixed to them, meshing with gears 425R and 425F (Figs. 1, 25, and 29). The gears 425R and 425F are keyed by keys 426 to the setting shafts 241. The progressive positions of the shafts 421R, in relation to the movements of the storage mechanism 161, can be seen in the sequence of Figures 6 and 16 to 17, inclusive.

Disabling the coupling hooks

When the permutation bar unit 300 moves upward near the end of its stroke, all of the yokes 400 of the selective control units are free to move up, in response to the pull of their springs 409, since it is the permutation bars coacting with the heads of pins 390 which holds them down. This upward movement, though terminated by the abutment of the shoulders 413 against the combs 411, is nevertheless sufficient to bring the hooks 407 above the level of the shoulders 408 of the latching dogs 123 or 124. The latching of the hammers by the dogs occurs after the permutation bar unit reaches its uppermost position and before it returns to its lowest position (compare, in Fig. 37, the curves entitled "Restore pins" and "Hammer cocking shaft"). Therefore, in order to prevent all of the latched hammers from being released by the hooks, on the downward movement of the permutation bar unit means are provided to prevent

the hooks of the coupling members from engaging the latching dogs of hammers which are to be latched in cocked position, until after the permutation bar unit has reached its lowest position. It will then have pulled the hooks of the coupling members below the level of the shoulders of the latching dogs and, upon being released at that time, the hooks will not hook over the shoulders.

For this purpose the latching bars 130 and 130a are provided with lugs 435 (Fig. 6) and 435a (Figs. 7 and 8) to engage fingers 436 on the coupling members 405, when the latching bars are given a setting movement to the left. The coupling members are thereby rocked to the position shown in Fig. 8 and are held in that position until the latching bars are released from the detents 143 and restored to their normal position at the right by the restoring vane 145. The timing is such that the coupling members strike the vertical faces of the shoulders 408 after the hook edges 407 have moved below the top of the shoulders 408. It is possible for the hook of a particular unit of the selective control mechanism to be above the shoulder 408 when the coupling member strikes the shoulder, on being released by the lug 435 or 435a. This will occur if the pins 390 of that selective control unit find a fit with the recesses of the permutation bars at the moment the permutation bar unit reaches its lower position. In this case the type member for which the selective control pins were set will be in printing relation to the corresponding column of the record sheet when the related hammer is released a moment later.

Type sequences in relation to the carriage movement

In the illustrative machine each type member 40 bears a single character. On the entire set of type members there are 151 type, namely, three complete sequences or repeats of 43 type characters each and 22 additional type bearing characters in the same sequence. A complete sequence, which is, of course, merely exemplary, is shown in Fig. 34, in the column headed "Character."

The type member carriage is mounted so as to travel longitudinally of the row of type members on it, and the direction of its travel is such that 50 each type member is presented in printing relation to a series of character spaces. In the illustrative embodiment shown, this series of character spaces is aligned across the record sheet. In other words, the type members are moved by the 55 travel of the carriage so that each one is presented to a series of columns in succession. This movement is sufficiently long to present to each individual column, at successive time intervals, an entire sequence of type members bearing all 60 the type characters the machine is adapted to print. If there should be only one complete sequence of type members on the type carriage, the stroke of the carriage would have to extend from a position in which all the type members are 65 ahead of the first column at one side of the sheet to a position in which all are beyond the last column at the other side of the sheet; a distance equal to the width of the record sheet plus the length of the single sequence of type members. 70 By increasing the number of type members, in repeats of the first sequence, and a final fraction of a repeat, to bring the length of the entire row of type members up to one repeat greater than the combined width of all of the columns of the

record sheet, the length of the stroke of the type carriage can be reduced to a little more than the length of one repeat, because this will be enough to present all of the type characters to each column.

The illustrative machine is designed for a record sheet 440 (Fig. 5) of 109 columns. The type member carriage is shown at the extreme left end of its stroke in Fig. 5. In this position the last type member at the right end of the first repeat is about eight spaces to the left of column 1. The movements of the permutation bar unit and type carriage are shown by the bottom two curves in the timing diagram (Fig. 37). In Fig. 5, the permutation bar unit and type carriage have just completed their movement to the left and are at 250° in the timing diagram (see also Fig. 28). At this point, the permutation bar unit starts a uniform low speed movement in the opposite direction, which continues to 324°. At about 286° it picks up the type carrier, which has remained stationary during the idle movement of the pin 373 toward the set screw 366. At 324°, the permutation bar unit and the type carriage, now moving as a unit, begin an acceleration, which continues to 360° and brings them to the uniform high speed movement toward the right. During the time described, from 250° to 360°, the permutation bar unit has moved a little less than six columns and the type carriage a little more than five columns. The permutation bar unit and type carriage now move at the uniform high speed for about 47 columns. During this time, the selective control mechanism releases the cocked hammers at the correct time to strike selected type members. The uniform high speed movement continues through a distance about four columns greater than the width of one repeat, in order to avoid the need for critical adjustment to insure operation of a type member which happens to be in printing position when the printing period begins, at 0°. The extra movement of the type carriage presents a few type members in the next sequence to each column, so that any hammer which failed to be tripped to strike the type member in the first sequence which passes it, will be tripped to strike the identical type member in the next sequence.

At the end of the uniform high speed movement the permutation bar unit and type carriage decelerate, from 234° to 250°, which brings them to the extreme right end of their movement. At this time, the type member at the left end of the first repeat stands about eight columns to the right of column 1. The operation during the return stroke of the permutation bar unit and type carriage is identical.

Circuit diagram and operation

The operation of the machine will be reviewed by referring to a particular example. It will be assumed that there are cards in the feed hopper 200 (Fig. 3) positioned to feed their 9 index points to the sensing brushes first. The bottom card will be assumed to be punched in twelve point alphabet code for the characters E1994 in columns 75, 76, 77, 78, and 79, respectively (see Fig. 38). Referring to the diagram in Fig. 34, and particularly to the column entitled "12 point code holes," it will be observed that the character E will be represented by perforations in the 5 and R index point positions, and the characters 1, 9, and 4 by single perforations in the 1, 9 and 4 index point positions, respectively. It

will be assumed, further, that the characters E1994 are to be printed in columns 103, 104, 105, 106, and 107, respectively, of the record sheet 440.

A simplified partial circuit diagram of the machine is shown in Fig. 36. Line current is supplied to the circuit through a main switch 441. The motor M is connected directly across the two sides of the lines 442 and 443. When the switch 441 is closed, the motor starts to run and turns the main shaft 17, but the card feed clutch dog 41 (Fig. 3) and printing mechanism clutch dog 19 (Fig. 2) remain disengaged. Operation of the start key closes contacts 444, completing a circuit from line 443 through contacts 444, card feed clutch magnet 45, the contacts 445 of the stop key to the other side of the line 442. The relay R5 in parallel with the card feed clutch magnet 45 is also energized and its contacts R5BU are closed to prepare the circuit of the print clutch magnet 30. The dog 41, upon release by the armature 46 of the card feed clutch drops onto the disk 40 and at 330° is engaged by the notch of the disk and starts the operation of the card feeding mechanism. During the first cycle, beginning at 0°, the first card passes under the upper brushes 22 (not shown in the circuit diagram), the functions of which are well known and will not be described here. At about 225° in the first cycle the card depresses the card lever 220, closing the contacts LCL and completing a circuit from line 443 through relay R3, contacts LCL, now closed, to line 442. The contacts R3AL of the relay R3 close, completing a holding circuit for the card feed clutch magnet 45 and relay R5 and the start key can now be released. The contacts R3BU of the relay R3 close, completing the circuit of the print clutch magnet 30 from line 443 through contacts R3BU and R5BU, now closed, magnet 30, to the line 442. The dog 19 drops onto the disk 40 and at 330° is engaged by the notch in the disk, starting the drive of the printing mechanism. It will be assumed that the permutation bar unit is at that one of its two stopping positions just past the right end of its stroke. It is accelerated to its uniform high speed movement to the left, which it attains at the start of the second cycle. No printing is performed during this stroke because no hammers are cocked.

The contacts R3BL of the relay R3 close, partly preparing the circuit of the lower brushes, to be described presently. The contacts R3AU of the relay R3 close, completing a holding circuit for the relay R3 through the contacts CF7, which circuit holds the relay R3 during the gap between cards feeding over the card lever 220. If the card lever 220 is not depressed when the contacts CF7 open at 270° (see timing diagram Fig. 37), the relay R3 is deenergized and the circuits of the card feed clutch magnet, the print clutch magnet, and the lower brushes are opened.

At the beginning of the second cycle the reading of the first card at the lower brushes begins. In preparation, the contacts CF2 (Figs. 3 and 36) are closed, see timing diagram (Fig. 37) preparing a circuit from line 442 through contacts R3BL and CF2, now closed, to the lower contact roller 219. As the lower brushes 218 find holes in their respective columns of the card, circuits are completed from each lower brush to its plug socket 446, a plug wire 447 to a plug socket 448, the related magnet 240, to line 443. In accordance with the example chosen, the lower brushes of columns 75, 76, 77, 78, 79 are plugged, respectively, to the magnets 240 of columns 103, 104, 105, 106, and 107 of the setting mechanism.

The storage mechanism 161, 162 is in the position shown in Fig. 6 and the setting mechanism 245, 246 has moved a little beyond the position shown in this figure, when the nine index point position of the card reaches the lower brushes. In the example the first card has 9 index points in columns 77 and 78, therefore the magnets 240 pertaining to columns 105 and 106 will be energized in time to drop the toes 193 of the storage plates ahead of the teeth 270a of the related setting disks 270 at the 9 index point position. Fig. 30 shows that disks 1 and 2 have teeth in the 9 position, hence the number 1 and 2 storage plates 160 of the storage units pertaining to columns 105 and 106 will be set up and the stirrups 170 cammed back into engagement with the armatures 241, in the manner described. The next index point to be sensed will be the 5 hole in column 75. This will release the storage unit for column 103 in time for the toes 193 of its storage plates 160 to drop in front of the teeth at the 5 position on the setting disks 270. Fig. 30 shows that disks 2 and 3 have teeth at this point and the 2 and 3 storage plates will accordingly be set, retatching the stirrup 170 with the armature 241. The next index point to be sensed is in column 79 at the 4 index point position, and this is followed by the sensing of an index point in column 76 at the 1 index point position. The No. 3 storage plate is accordingly set in column 107 (see Fig. 30) and the 1 and 4 storage plates in column 104. Finally an index point is sensed in column 75 at the R position, tripping the storage unit for column 103 a second time, in time to catch a single tooth on the No. 6 setting disk. Thus, the final setting in column 103 leaves storage plates 2, 3, and 6 in set position. The reading of the card ends at 216° and by 234°, the setting of the No. 6 storage plate in column 103 is finished.

At 252° in the second cycle, the cams 186 and 187 begin to rock the shaft 120 in clockwise direction (Fig. 25). The two assemblies of the storage mechanism, the setting of which has been completed, begin to rock inward, to transfer their settings to the pins of the selective control mechanism. Fig. 17 illustrates the transfer taking place in column 104, where the 1 and 4 storage plates have been set.

The clockwise rocking of the shaft 120 also retracts all of the printing hammers to the position shown in Fig. 8, this movement being finished at 300°. During approximately the same period, the latching bars 130 and 130a in columns 103 to 107 are being moved to the left by engagement of the set storage plates in these columns with the operating levers 136 and 140. Thus, when the hammers in columns 103 to 107 reach the position shown in Fig. 8, the latching dogs 123 and 124 for these hammers spring in front of the shoulders 128. The shaft 120 returns to the normal position shown in Fig. 7 by 360°, all of the printing hammers except those pertaining to columns 103 to 107 returning with it. The latching bars 130, 130a in columns 103 to 107 remain latched by the spring detents 143, holding the coupling members 405 in the inoperative position shown in Fig. 8. At 357° the vane 145 releases these latching bars from the spring detents and moves them to the right, restoring the coupling members to the operative position shown in Fig. 6 at approximately 360°. The storage plates, having transferred their settings by 300°, are restored to normal position by the vanes 420R and 420F between 324° and 358°.

At the beginning of the third machine cycle, the mechanisms described are ready to begin the second card reading cycle and the first printing cycle. By the time the permutation bar unit has been accelerated toward the right to its high uniform speed, at the beginning of the third cycle, the type carriage has moved from the position shown in Fig. 5 to the position in which the type member bearing the character "4" is approaching printing relation to column 107. It will be assumed that at the moment the permutation bar unit reaches its lowest position and the coupling members 405 are restored to the operative position, (Fig. 6), which occurs at the beginning of the cycle, the pins 390 of the selective control unit pertaining to column 107 find a fit with the recesses of the permutation bars. The diagram in Fig. 34 shows that the No. 3 pin in this unit is set and the other five pins are unset, and also shows the zone of the permutation bars which will be found by this group of pins when the permutation bar unit reaches its lower position. It will be the second zone from the right end, since the sequence terminates with the character D, at the right end (see Fig. 34). The coupling member of column 107 will accordingly be engaged over the shoulder 408 of the latching dog 124 of this column when the permutation bar unit reaches its bottom position. Immediately afterward the ends of the clearance recesses on permutation bars 2 and 5 will cam the related pins down and release the printing hammer of column 107.

If it should occur that the pins of the selective control unit for column 107 are already out of the recesses of the permutation bars in the zone pertaining to the character "4," at the moment the permutation bar unit reaches its lower position, preventing the coupling hook from engaging over the shoulder of the latching dog, the character "4" will nevertheless be printed in column 107, but at a later time. The permutation bar unit continues its movement at the uniform high speed for forty-seven columns and the same combination of recesses occurs in the permutation bars, together with another type member bearing the character "4," forty-three columns from the first one near the right end. The hammer of column 107, being still latched, will be released at the correct time to strike the second type member bearing the character "4." If the first type member bearing the character "4" is actuated, the second occurrence of the same combination in the permutation bars will be without effect, because the hammer will already have been tripped.

Shortly after the printing of the character "4" in column 107, in the manner first described, the type member bearing character E approaches printing relation to column 103, as the pins of the selective control unit pertaining to this column find a fit with the recesses of the permutation bars. The character E is printed in column 103 in the same manner as the character "4" was printed in column 107.

The next action to occur is the printing of a nine in column 105, followed immediately by the printing of a nine in column 106. For this sequence of actions, it is essential that the type member bearing the "9" type move from its position of rest to print in column 105 and back to a stable position of rest, within the interval between the instants when it is struck by the hammers of columns 105 and 106. If it should be late in returning to the position of rest, or should

be rebounding from the rest position at the instant the hammer of column 106 arrives in the normal striking position, the type member will either not be struck at all or will be struck abnormally. The V-notches of the abutment bar 93 (Fig. 13) prevent the type member from rebounding and thereby insure its correct actuation, even for the repeat operation described.

The last printing action in this cycle is the printing of the character "1" in column 104. It will be noted that the order of the printing in the different columns varies at random, depending upon the particular characters to be printed. In general, the printing is distributed through a large part of the printing portion of the cycle.

To demonstrate the type member action in greater detail, Fig. 23 shows the position of the type member 90 bearing character "1," in relation to a hammer 100 and column 93 of the record sheet, at the instant the coupling member 405 releases the latching dog 124 from the shoulder 128 of the hammer 100. The release is effected by the camming action of the permutation bars 302—1, 5 upon the pins 390—1, 5, which are connected to the coupling member by the yoke 400, as indicated by the dash line. The permutation bars and the type member are moving in the direction of the arrows in this figure. The hammer, upon being released, is thrown by the driving lever 103 (Fig. 7) against the type member, striking the latter an instant before the type member reaches column 93 of the record sheet. The hammer travels a short distance with the type member, as indicated by the dash line in Fig. 7, then is stopped by the abutment 114. The type member continues under its own momentum and by the time it strikes the record sheet, it is directly in line with column 93. During the brief time the type member is in contact with the record sheet, through the ribbon 49, the head 94 of the type member turns counterclockwise on its pivot 95. The normal position of the head of the type member on its pivot is restored by the tapered sides 90a, in the manner previously described, as the type member rebounds to its position of rest, pulled by the spring 81.

If the type member carriage and permutation bar unit had been moving in the opposite direction, the conditions would have been as shown in Fig. 24, at the time of the release of the hammer 100 by the latching dog 124. The release occurs when the type member 90 is about one-half column away from the column in which it is to print. The relative movement between the type member carriage and the permutation bar unit permitted by the lost motion connection between the pin 373 and the set screws 366 and 367, provides for the difference in position of the type member as it approaches a particular column of the record sheet from opposite directions. In Fig. 24, the release of the latching dog is effected by the permutation bar 302—6, as can be seen by examining the recesses of the permutation bars in Fig. 34, in the zone pertaining to the character "1." When the type strikes the record sheet this time it wobbles clockwise on its pivot 95. The striking movement of the hammer is so rapid that a rebound checking pawl 450, pivoted on a rod 451 and biased counterclockwise by a spring 452 bearing on the lower bar 111, jumps over a deep notch 453 in the upper edge of the hammer, as shown in Fig. 20, and lands upon the ledge 454. When the hammer rebounds to the left, the pawl 450 drops into the notch 453, as shown in Fig. 7, and holds the head of the ham-

mer clear of the ends of the type members. The rebound of the hammer from the type member is ordinarily so fast that it clears the type member next to the one struck by it, as the movement of the type member carriage continues. However, the hammer may be provided with a pivoted head 455, which can turn aside if the hammer should not rebound quite fast enough for the head to miss the end of the next type member. The tilting head is restored to the normal position when the hammer is cocked, by the sides of the bearing 101 (Fig. 6).

During the printing operation, which is completed between 0° and 216° (see the timing diagram) the reading of the second card is taking place, accompanied by the storage of the characters sensed, in the storage mechanism. Thus, the printing and the reading occur simultaneously during one portion of the cycle, while the transfer of the code settings from the storage mechanism to the selective control mechanism occurs in the intervals between the portions of two successive cycles during which the printing and setting occurs.

Some constructional features

The hammer and latch bar mechanism is mounted in a frame which is detachable as a unit, or preferably in a plurality of units. This frame is composed of a series of specially shaped thin plates 460 (Fig. 6) which are united by various rods and shafts, such as the shaft 104 of the impelling levers 103 and the shafts 125 and 126 on which the latching dogs are pivoted. If the frame is composed of a plurality of units, these shafts will of course be sub-divided. The plates 460 are spaced apart by the bearings 101, 131 and 132. The hammers and latching bars are mounted in pairs, in spaces between the plates 460. The constructions of the bearings which support the hammers and latching bars are shown in the detail views, Figs. 10, 11, and 12. The bearing for the head end of each pair of hammers 100 is a single block 461 having two grooves on its opposite sides to receive the two hammers. Between the hammers and the plates 460 are two thin spacing members 462. The blocks 461 and the spacing members 462 are held in place by rods 463, which extend the full length of the frame, or the length of one unit of the frame, and which also serve to tie the plates 460 together.

The bearings 102 for the left ends of the pairs of hammers 100 are divided into two bearing blocks 465 and 465a. These blocks have grooves on their opposite sides to receive the hammers 100 and spacing members 466 are also provided between the hammers and the plates 460. The spacing members are held in place by small pins 464 thereon fitting into holes in the blocks 465, 465a. The top ends of the bearing blocks 465 and 465a have threaded holes 467 to receive screws 468, the heads of which rest upon a bar 469 extending the length of the frame, or the length of one unit of the frame. By turning the screws 468, the bearing blocks 465 and 465a can be raised or lowered, for a purpose to be presently described.

The bearings 132 for the left ends of the latching bars 130 and 130a are similar to the bearings 101. For each pair of latching bars 130, 130a, there is a single bearing block 470, with grooves on its opposite sides to receive the latching bars. Spacing members 471 are provided and are held in position with the bearing blocks by

tie rods 472. A screw 473 passing through the bearing block 470 and screwed into a small oblong nut 474 guides and holds the lower ends of the bearing blocks 465 and 465a, as shown in Fig. 11. When the latter bearing blocks are to be adjusted the screw 473 is loosened, then tightened again, after the screws 468 have been adjusted, to clamp the bearing blocks 465 and 465a.

The bearings 131 are similar to the bearings 132 and need no particular description or detail illustration.

The plates 460 are notched at 480 to engage a flange 481 on the bolster 391. The notches are shaped to permit the frame, or a unit thereof, to be engaged with the flange, with its forward side tilted upward, and to be rocked down to the position shown in Fig. 6. A plate 482 secured to cross bar 483 by screws 484, holds down the front end of the plates 460. Blocks 485 screwed to the top bolster retain the frame, or its individual units, against lateral shifting.

Adjusting character spacing

The spacing of the characters on the record sheet can be adjusted by changing the time of release of the hammers by their latching dogs. The downward movement of a particular latching dog by its coupling member always takes place in exactly timed relation to the movement of the type carriage, since it is determined by the positive camming action of the permutation bars upon the pins of the selective control unit. By raising or lowering the left end of the hammer (Figs. 6 and 8), the exact time at which the latching dog will clear the bottom end of the shoulder 128 can be changed. This is the purpose of the adjustability of the bearing blocks 465 and 465a.

Zero printing

It was previously mentioned that the single setting of a No. 5 storage plate 160 would not cause the related hammer to be latched in the cocked position, because the No. 5 storage plate is too short to reach the operating lever 136 or 140, even when set up. Thus, even though the selective control pins 390 will be set for the character "0" and will accordingly respond to that zone of the permutation bar unit, the character "0" will not be printed in the related column, unless a further control, now to be described, becomes effective. The purpose of this arrangement is to control the printing of zeros in dependence upon the occurrence of a significant digit to the left, a procedure well known in tabulating machine operation. This is accomplished, in the present machine, by interlocking devices provided on the latching bars 130 and 130a. Each of the latching bars has pivoted to it a small detent 490 (Fig. 6) with a bent over end 491. When the detent is in the position shown it is inoperative, but when it is rocked 90° counterclockwise, the bent over end 491 falls in front of a shoulder 492 on the next latching bar to the left. In this case, if the detents 490 on the latching bars pertaining to columns 108 and 109 are down, in operative position, and a significant digit is entered in column 107, the shoulder 492 of the latching bar of column 107 will strike the detent 490 of the latching bar of column 108 and operate said latching bar. Likewise, the latching bar of column 109 will be operated by the latching bar of column 108. Thus the hammers of columns 108 and 109 will be cocked and will be released, under control of

the related units of the selective control mechanism, to print zeros. The detents 490 are made rockable in order to break the control of zero printing between different fields of the record sheet.

Response to different codes

One of the important features of the invention is the ability of the machine to respond in the same way to identical characters represented in different codes on the control cards. Fig. 34 shows two codes on opposite sides of the column entitled "Character," namely, a 6 point code on the left and a 12 point code on the right. In the illustrative example previously described, the card was assumed to be punched in the 12 point code. If it had been punched in the 6 point code, the result would have been identical, without the need for setting the machine, either manually or automatically. To follow through the same example in the 6 point code, it will be observed that for the character E in column 75, the card would be punched at the 6, 4, and R index point positions. In response to the 6 hole, the No. 2 storage plate 160 would be set up (see Fig. 30), the 4 hole would cause the No. 3 plate to be set, and the R hole would cause the No. 6 plate to be set. The final setting, 2, 3, and 6, is the same as that caused by the 5 and R holes in the 12 point code. For the character "1" the 6 point code calls for an 8 and a 2 hole. The 8 hole will result in setting the storage plate 1 and the 2 hole will cause the storage plate 4 to be set. This is the same setting caused by the single hole at the 1 index point, in accordance with the 12 point code. In the same way, it will be found that the setting of the storage plate caused by 12 point code holes is always identical to the setting caused by 6 point code holes for the same character.

It is evident that to change the set of type of this machine is a very simple matter. It is only necessary to pull up the pin 370 and to draw out the type member carriage; then to insert the new type member carriage and insert the pin 370 on the same into the space between the set screws 366 and 367. Any change of the type characters in the set will of course give a different meaning to the code perforations of the control cards.

The striking of the type members, in the described machine, is distributed and not simultaneous, as in most of the machines in use at present. This reduces the shock and vibration of the machine. At the same time, the impact of the individual type members is powerful and enables the machine to print a large number of carbon copies. Furthermore, the force with which the type strikes the paper varies automatically, in direct ratio to the thickness of the paper pack on the platen, which is determined by the number of carbon copies being printed. This is so because the type member, at the time it strikes the paper, is moving under its own momentum. From the time it leaves the hammer its kinetic energy is dissipated by friction and translated in its spring 81, so that the shorter the distance it travels to strike the paper the more energy it will have and the greater will be its impact against the paper pack. Because of the shortness of the stroke of the type member, its deceleration curve can be made sufficiently steep, so that a reduction of the distance between the type member and the paper, at the start of the free movement of the type member, by the five thousandths of an inch, more or less,

by which one sheet each of record paper and carbon paper thicken the paper pack, increases the impact by enough to print another carbon copy.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In a mechanism for printing a plurality of characters in a plurality of aligned character spaces of a record sheet, a group of type members bearing different characters, means to cause said group of type members to execute a single stroke movement such that each type member comes into printing relation with all of said character spaces, adjustable means associated with each character space adapted to detect the approach of any selected type member of said group to the related character space, and means controlled by said detecting means to actuate said selected type members to print in the related character spaces, in the order in which they arrive thereat in the course of said single stroke movement, whereby at least a plurality of said spaces receive printed impressions in the course of said single stroke movement.

2. In a mechanism for printing a plurality of characters in a plurality of aligned character spaces of a record sheet, a group of type members bearing different type characters, means for moving said type members in succession along the line of said character spaces, settable means associated with each character space for detecting the arrival of any selected type member of said group at a certain position in relation to the respective character spaces of said line, and means controlled by said detecting means for causing said selected type members to print in said respective character spaces.

3. In combination with a support for holding a record sheet to present an area thereof comprising a plurality of character spaces, in impression receiving position, a type bar mounted for longitudinal movement parallel to said area and having a row of different type members thereon adapted to be individually actuated to print on said area, and means for selectively actuating said type members to print in different ones of said character spaces in the course of a movement of said type bar in one direction, said last means being adjustable to select for actuation, independently for each of said character spaces in which a character is to be printed, any one of said type members.

4. The combination with a support for holding a record sheet to present an area thereof in impression receiving position, of a plurality of type members mounted so as to be movable as a group parallel to said area of the record sheet, said type members being individually actuatable to make an impression on said area and positioned so that in any one position of the group different type members are in printing relation to different character spaces of said area of the record sheet, while during said group movement different type members come into printing relation to the same character spaces of said area, and

means for selectively actuating said type members to print in a plurality of said character spaces during their movement as a group in one direction, said last mentioned means being adjustable to select for actuation, independently for each of said character spaces in which a character is to be printed, any one of said type members, and to actuate said selected type members in the order in which they arrive at the character spaces in which they are to print.

5. Printing means as described in claim 2, wherein said detecting means comprises identifying means for each of the individual type members differentiated from each other so that each designates the particular character carried by the related type member and a sensing device associated with each character space adjustable to coact with the identifying means designating any one, and only one, of the characters on the type members, said identifying means being movable with said type members so as to be brought into coacting relation with said sensing devices.

6. In a printing mechanism, in combination with means to support a record sheet, a group of type members bearing different characters, means to impart a unidirectional movement to said group of type members such that each of said type members is presented in printing relation to each one of a series of character spaces, detecting means comprising a plurality of individually settable units, one for each of said character spaces, each unit being settable to detect the arrival, during said unidirectional movement, of any one, and only one, of said type members at a certain position in reference to the related character space, means for setting the individual units to detect particular type members of the group, and means controlled by said detecting means to actuate said selected type members to print in the related character spaces.

7. In a printing mechanism, a platen, a row of printing actuators in uniform spaced relation to said platen mounted for individual movement toward the platen, a group of type members bearing different type characters, means to move said type members in sequence at uniform speed through the space between said row of printing actuators and said platen, in one direction parallel to the row of actuators and selective control means to initiate operative movements of said printing actuators during said movement of the type members, each at a time slightly in advance of the arrival of any particular type member in direct opposition thereto.

8. In a printing mechanism, a line of independently operable printing actuators, a type carrier having a row of type members thereon, parallel to said line of actuators, means to reciprocate said type carrier longitudinally of the row of type members thereon so as to move said type members in sequence past said actuators, means operating between reciprocations of said type carrier to condition said printing actuators for a single operation of each, and selective control means for causing the single operations of said printing actuators to occur at differential times in one stroke of said type carrier, to strike a plurality of selected type members of said row.

9. In a mechanism for printing a plurality of characters in a plurality of aligned character spaces of a record sheet, a line of printing actuators positioned in spaced relation to, and parallel to, the line of said character spaces, one printing actuator being opposite each character space; a row of type members parallel to the

line of said character spaces, means for moving said type members in one direction longitudinally of said row, through the space between said printing actuators and the record sheet, so that a succession of said type members passes between each printing actuator and its related character space; settable means associated with each character space for detecting the approach of any selected one of said type members to the related character space, in the course of said movement of the type members in one direction; and means controlled by said detecting means for causing the individual printing actuators to actuate said selected type members to print in said character spaces, respectively.

10. The combination with a support to hold a record sheet for printing thereon, of a group of type members mounted in a row parallel to the record sheet and bearing various type characters; means to cause said type members to travel longitudinally of the row along a plurality of aligned character spaces of the record sheet; a group of printing actuators, one for each of said character spaces, mounted in a row opposite their respective character spaces, and adapted, when operated, to cause individual type members presented to them in the course of the travel of said group of type members, to print in the character spaces pertaining to the respective printing actuators; control means for selecting, for each character space independently, any one of said type characters to be printed therein; and means controlled by said control means, to operate said printing actuators individually, each at the time when the type member bearing the character selected for printing in its particular character space is presented to it in the course of said movement of the group of type members.

11. In a printing mechanism, in combination with a support to hold a record sheet, a series of selecting devices, each pertaining to a particular character space of the record sheet, and each individually settable to represent any one, and only one, of a plurality of different characters; a set of type members, each bearing a different one of said characters; type member actuating means controlled by said selecting devices; means for moving said type members in sequence along the record sheet past said character spaces; and means controlling each selecting device in dependence upon the setting thereof to cause an actuation of the particular type member bearing the character said selecting device is set to represent, as said type member arrives in printing relation to the character space pertaining to said selecting device.

12. The combination with a support to hold a record sheet for printing thereon, of a group of type members mounted in a row adjacent said support, so as to travel longitudinally of the row, means for moving said group of type members through a stroke of uniform length, first in one direction and then in the opposite direction; and means whereby any selected type member of the group can be caused to print upon the record sheet in the course of the travel of the group of type members in either direction.

13. In a mechanism for printing a plurality of characters in a plurality of aligned character spaces of a record sheet, a group of type members bearing different type characters, means for moving said type members in succession along the line of said character spaces, means for detecting the arrival of particular type members of said group at a certain position in relation to par-

ticular character spaces of said line, said detecting means comprising a plurality of cam elements movable in synchronism with said group of type members and differentiated from each other to designate, respectively, the various type characters on said type members, and a plurality of control devices associated with the respective character spaces and adapted to sense said cam elements in succession, each control device being individually settable to coat with any one, and only one, of said cam elements, and means controlled by said control devices, when the latter sense the cam elements for which they are set, to cause the type members bearing the related type characters to print in the respective character spaces to which the control devices appertain.

14. In a mechanism for printing a plurality of characters in a plurality of aligned character spaces of a record sheet, a line of spring actuated printing hammers positioned in spaced relation to the line of said character spaces, one hammer being opposite each character space; means for individually latching said hammers in cocked position; a group of type members; means for moving said type members along the line of character spaces through the space between said hammers and the record sheet, so that a succession of said type members passes between each hammer and its related character space; settable means for detecting the approach of selected type members to particular character spaces; and means controlled by said detecting means for operating the individual latching means, to release their respective hammers so as to cause the selected type members to print in said particular character spaces, respectively.

15. A printing mechanism as described in claim 14, wherein said detecting means comprises a plurality of selecting units, one for each of said printing hammers; means for individually setting said selecting units; and means controlled by said setting means for latching in cocked position the printing hammer pertaining to any selecting unit which is set.

16. A printing mechanism as described in claim 14, wherein said detecting means comprises a plurality of selecting units, one for each of said printing hammers; a plurality of setting units, one for each selecting unit, each setting unit comprising a group of elements each of which has a normal position and a set position, said setting units being movable to set their related selecting units in accordance with the combinational setting of their elements, and means including devices controlled by elements in set position, during the setting movements of said setting units, for latching in cocked position the printing hammers pertaining to their respective selecting units.

17. A printing mechanism as described in claim 14, wherein said detecting means comprises a plurality of selecting units, one for each of said printing hammers; a plurality of setting units, one for each selecting unit, each setting unit comprising a group of elements each of which has a normal position and a set position, said setting units being movable to set their related selecting units in accordance with the combinational setting of their elements; one of said elements of each setting unit, when alone in set position, representing a "zero"; and means including a device controlled by any of said elements, except said "zero" elements, during the setting movement of said setting units, for latch-

ing in cocked position the printing hammers pertaining to any setting units having a set element other than a zero element.

18. A printing mechanism as described in claim 14, wherein said detecting means comprises a plurality of selecting units, one for each of said printing hammers; a plurality of setting units, one for each selecting unit, each setting unit comprising a group of elements each of which has a normal position and a set position, said setting units being movable to set their related selecting units in accordance with the combinational setting of their elements; one of said elements of each setting unit, when alone in set position, representing a "zero"; and means including a device controlled by any of said elements, except said "zero" elements, during the setting movement of said setting units, for latching in cocked position the printing hammers pertaining to any setting units having a set element other than a zero element, said cocking means comprising an individual latching member for each hammer, at least some of said cocking members having means interconnecting each with a neighboring latching member, whereby a latching operation of one is accompanied by a latching operation of the other, independently of the setting of the setting unit pertaining to the latter.

19. In a printing mechanism, in combination with means to support a record sheet to present a line of character spaces in position to receive printed characters, a group of type members arranged in a row parallel to said line of character spaces and mounted so as to be movable as a group, longitudinally of the row, each type member bearing a different character; a row of printing actuators arranged at one side of the path of movement of said type members and parallel to said line of character spaces; means to move said type members as a group, longitudinally of the row, so that all of said type members in turn pass each of said printing actuators; differentiated identifying means for each different character of said type members, said identifying means being movable with, and positioned in a certain relation to the related type members as the latter move; individual selecting means for each of said printing actuators, each selecting means being positioned in a certain relation to its related printing actuator and adjustable to coact with the identifying means pertaining to any one, and only one character as said identifying means move; and means controlled by each selecting means, to cause an operation of the related printing actuator when the identifying means pertaining to a selected character coacts with said selecting means.

20. A printing mechanism as described in claim 19, wherein each selecting means comprises a set of permutation members individually movable to different positions, to present to the passing identifying means a particular arrangement of sensing surfaces adapted to coact only with the identifying means pertaining to a particular character.

21. In a printing mechanism, a group of type members arranged in a row and mounted so as to be movable as a group, longitudinally of the row; a printing hammer arranged at one side of the path of movement of said type members; a latch to hold said hammer in cocked position; means to support a record sheet to receive an impression from a type member actuated by said printing hammer; means to move said type members as a group, longitudinally of the row, so that

all of said type members in turn pass said printing hammer; identifying means movable with said type members and having differentiated cam means for each type member, positioned in a certain relation to its type member, as the set of type members moves; selecting means comprising a yoke mounted for limited movement and having a set of permutation members thereon adjustable to coact with any one, and only one, of said cam means; spring means yieldably urging said yoke in one direction to cause its permutation members to sense the passing cam means, said selecting means executing a movement in one direction, by the force of said spring means, on sensing the particular cam means for which it is set, and then a movement in the opposite direction by the camming action of said cam means; a hammer releasing member having means to engage said latch, but normally disengaged therefrom; said releasing member being connected to said selecting means so as to be moved to engage said latch as said selecting means moves in said first direction and to retract said latch and release said hammer, as said selecting means moves in said opposite direction.

22. In a printing mechanism, a line of printing actuators; a row of type members each bearing a particular type character and the entire row bearing at least one complete set of type characters, said type members being mounted so as to travel as a group, in the longitudinal direction of the row, to present a succession of said type members in printing relation to each of said printing actuators; a line of selecting units adjacent said line of printing actuators, one unit for each printing actuator; identifying means for the individual type members differentiated from each other so that each designates the particular character carried by the related type member, said identifying means being mounted to travel with the type members, so as to pass said selecting units, the timing being such that as each identifying means reaches a given selecting unit the related type member reaches a certain position in relation to the printing actuator pertaining to said selecting unit; each of said selecting units being settable to coact with any one, and only one, of said identifying means; means to cause said type members and associated identifying means to travel; first in one direction and then in the opposite direction; and means whereby said selecting units can be set to new positions as said type members reach the end of their travel in either direction; said selecting units being adapted to coact with the identifying means for which they are respectively set, as said type members travel in either direction, to initiate operations of their respective printing actuators.

23. A printing mechanism as described in claim 24, wherein said identifying means and said group of type members are interconnected so as to have limited free relative movement, whereby their relative position shifts upon reversal of their travel.

24. In a printing mechanism, a frame, a type member carriage mounted to reciprocate in said frame and bearing a set of spaced individually movable type members, a cam bar mounted in said frame to reciprocate parallel to said carriage and bearing mutually differentiated cam elements spaced proportionally to the type members, a printing actuator positioned so that said type members pass in printing relation thereto as said carriage reciprocates, selective control means for said printing actuator comprising feeler means

adapted to cooperate with said cam elements, and means connecting said cam bar to said carriage so that as the latter reciprocates said cam elements move successively into operative relation to said feeler means as said type members successively approach said printing actuator, said feeler means being adjustable to respond to any one, and only one, of said cam elements, to initiate an operation of said printing actuator.

25. A printing mechanism as described in claim 24, wherein said selective control means comprises a normally disengaged coupling member which is moved alternately in opposite directions by the movement of said feeler means in response to one of said cam elements, said coupling member being adapted to be coupled by its movement in one direction and to initiate the operation of said printing actuator by its movement in the opposite direction.

26. In a printing mechanism, a row of printing actuators, a set of type members mounted in a row parallel to said row of printing actuators, means for moving said row of type members longitudinally so that all of said type members in succession pass said printing actuators, a set of mutually differentiated identifying means associated with said set of type members so as to travel in unison therewith, each type member having distinct individual identifying means of said set associated therewith, the relative position of each type member and its associated identifying means being the same for all type members, and individual control means for each of said printing actuators, each of said control means including means to sense said identifying means, the sensing means of each control means being settable to coat with any one, and only one, of said identifying means, to cause an operation of the related printing actuator at the time the type member associated with said one identifying means arrives at a certain position in relation to said related printing actuator.

27. In a printing mechanism, a frame, a carriage and a bar both mounted in said frame so as to move along paths parallel to the long axis of said bar, means interconnecting said carriage and said bar so that they are constrained to move in unison, means to reciprocate said carriage and bar, a series of type members on said carriage, a printing actuator past which said type members are moved as said carriage travels, and selective control means to control the operation of said printing actuator, comprising settable means to sense said bar, said bar having a series of mutually differentiated identifying means thereon, one for each type member, positioned so as to meet said sensing means as their related type members approach said printing actuator, said sensing means being settable to coat with any one, and only one, of said identifying means as said bar and carriage move in either direction of their reciprocation, to cause an operation of said printing actuator.

28. A printing mechanism as described in claim 27, wherein the means interconnecting said carriage and said bar is a loose connection permitting a limited relative shift of position of said carriage and said bar.

29. In a printing mechanism, a frame, a carriage and a bar both mounted in said frame so as to move along paths parallel to the long axis of said bar, said bar having a plurality of notched ledges thereon parallel to its long axis, means interconnecting said carriage and said bar so that they are constrained to move in unison, means

to reciprocate said carriage and said bar, a printing actuator past which said type members are moved as said carriage travels, and selective control means to control the operation of said printing actuator, comprising a group of settable elements, one for each of said ledges, and means including a yoke yieldably pressing said elements against their respective ledges as said bar moves, the notches of said ledges being arranged in different permutations so that each group of notches sensed by said elements at one time will fit only one setting of said elements, and means operated by said yoke, on sensing a fit with said notches, for initiating an operation of said printing actuator, said groups of notches being respectively associated with the different type members and being positioned on said bar so that each group is sensed as the related type member approaches said printing actuator.

30. In a printing mechanism, a type member carriage, a set of type members thereon, a paper support adapted to support a sheet of paper so as to present a line of character spaces at one time in position to receive printed impressions, means to reciprocate said carriage with a uniform full-stroke movement parallel to said line of character spaces, so that all of said type members pass in sequence before each of said character spaces during each stroke, and selective control means operated at differential times during one full stroke movement of said carriage to cause selected type members to print in a plurality of said character spaces.

31. In a mechanism for printing a plurality of characters in a plurality of aligned character spaces of a record sheet, a line of normally disabled printing actuators positioned in spaced relation to, and parallel to, the line of said character spaces, one printing actuator being opposite each character space, a line of type members parallel to the line of character spaces, means for moving said line of type members in one direction through the space between said printing actuators and the record sheet, so that a succession of said type members passes between each printing actuator and its related character space, settable means associated with each character space for detecting the approach of any selected one of said type members to the related character space in the course of said movement in one direction, means coordinated with said type member moving means so as to act before the type members are moved along the line of printing actuators, for setting said detecting means and for enabling the related printing actuators for a single operation of each, and means controlled by said detecting means for causing one, and only one, operation of each of the enabled printing actuators, in the course of said movement of the type members in one direction.

32. In a printing mechanism, a line of independently operable printing actuators, a type carrier having a row of type thereon parallel to said line of actuators, means to reciprocate said type carrier longitudinally of the row of type thereon, so as to move said type in sequence past said actuators, a series of selective control units, one for each of said printing actuators, and a series of identifying means, one for each type, arranged in the same order as the type and adapted to reciprocate with said type carrier, so as to pass in sequence in coating relation to all of said selective control units in succession.

33. In a printing mechanism, a printing actua-

tor, a plurality of type members bearing different characters, means for presenting said type members successively in position to be operated by said printing actuator, selective control means comprising a group of selecting elements each having a plurality of positions, identifying means having a series of mutually differentiated identifying parts representing, respectively, the different type members, means to set said selecting elements in various combinational positions, each combination conforming to a different one of said identifying parts, said group of selecting elements and said identifying means having relative movement in two different directions, the relative movement in one direction causing said identifying parts to be presented successively to said selecting elements in synchronism with the presentation of the different type members to said printing actuator, the relative movement in the other direction resulting from the finding of an identifying part conforming to the setting of said selecting elements, and means controlled by said last mentioned relative movement for operating said printing actuator.

34. In a printing mechanism, a printing actuator, a plurality of type members bearing different characters, means for presenting said type members successively in position to be operated by said printing actuator, selective control means comprising a group of selecting elements each having a plurality of positions, identifying means having a number of cam surfaces coating, respectively, with said selecting elements, means operating in synchronism with said type member presenting means to move said identifying means in relation to said selecting elements, said cam surfaces having, at successive parts thereof simultaneously presented to said selecting elements, various combinations of contours, each conforming to a different setting of said selecting elements, and means operated by said selective control means on finding a conforming contour for causing an operation of said printing actuator.

35. In a printing mechanism, a row of printing actuators, a type member carrier mounted for movement parallel to said row of printing actuators, individually movable type members mounted on said carrier in a row parallel to said row of printing actuators, said type members comprising a plurality of complete sets of type, means for reciprocating said type carrier through a stroke of sufficient length to cause a complete set of said type to pass each of said printing actuators in position to be actuated thereby, and means to operate said printing actuators at differential times in the course of one stroke of said type carrier.

36. In a printing mechanism, a platen, a carriage mounted so as to travel along said platen, a group of type members mounted on said carriage so as to be individually movable toward different points on said platen, when said carriage is in any one position, means to move the carriage along the platen, and preset means selectively to actuate a plurality of said type members toward different points along said platen as the movement of the carriage progresses in one direction.

37. In a printing mechanism, a platen, a carriage mounted so as to travel along said platen, a row of type members bearing different type characters mounted on said carriage equidistantly from said platen, means to move said carriage along said platen, and means selectively to actuate a plurality of said type members toward

different points along said platen as the movement of the carriage progresses in one direction.

5 38. In a printing mechanism, a set of type members, means to move said type members in sequence along a prescribed path, means acting in the course of one movement to move a plurality of individual type members of the set transversely to said path at different points along said path, and means to support a record sheet in position to receive impressions from said transversely moved type members at said different points.

10 39. In a printing mechanism, a frame, a carriage mounted to reciprocate in said frame, means to reciprocate said carriage, a row of type members, each comprising a body portion guided in said carriage for movement transverse to the direction of reciprocation of the carriage and a type bearing head freely pivoted to said body portion on an axis perpendicular to both said reciprocating and transverse movements, spring means adapted to hold said head in a normal position, means to impel individual type members in said transverse direction during the movement of the carriage, and means to support a record sheet 15 to receive impressions from type members so impelled.

20 40. In a printing mechanism, a frame, a carriage mounted to reciprocate in said frame, means to reciprocate said carriage, a row of type members, each comprising a body portion guided in said carriage for movement transverse to the direction of reciprocation of the carriage and a type bearing head pivoted to said body portion on an axis perpendicular to both said reciprocating 25 and transverse movements, individual retracting springs for said type members and stop means on said carriage to determine the rest position of the type members, said springs being adapted to hold the head portions of the type members in a normal position in reference to the related body portions, means to impel individual type members away from said rest position in said transverse direction, during the movement of the carriage, and means to support a record sheet to receive 30 impressions from type members so impelled.

45 41. Printing mechanism as described in claim 40, wherein said retracting springs are stretched between the carriage and a portion of the head of the related type member on the side of said 50 pivot remote from said support.

42. Printing mechanism as described in claim 40, wherein said type members are guided in individual slots in said carriage, the heads of the type members having a sliding fit in the related 55 slots and the sides of said heads being tapered in the direction away from said support, whereby when a type member is impelled its head becomes free to rock on its pivot, while on the return of the type member to position of rest said tapered sides normalize the head of the type member with respect to said support.

43. Printing mechanism as described in claim 40, wherein abutting portions of said stop means and said type members are provided with complementary bias surfaces adapted to check the rebound of the type member from the stop means.

44. Printing mechanism as described in claim 39, wherein the pivotal connection between the head and body of each type member is loose and the head and body are provided with complementary abutting arcuate surfaces concentric to the axis of their pivotal connection.

70 45. In a printing mechanism, a paper support,

a printing hammer spaced from, and mounted to move toward and away from said paper support; a carriage, a row of type members thereon, said carriage being mounted so as to move said type members through the space between said printing hammer and said paper support and said type members being mounted on said carriage so as to be individually movable toward and away from said paper support, means to propel said hammer toward any type member interposed between the same and said support, means to stop said propelling means before said hammer strikes said type member, the connection between said propelling means and said hammer being adapted to allow the hammer to continue by its momentum, and means to stop said hammer after it strikes said type member and before the latter strikes the paper on said support.

46. In a printing mechanism, a paper support, a frame adjacent thereto, a printing hammer mounted on said frame for free movement toward and away from said support, propelling means having lost motion engagement with said hammer for propelling the latter toward said support, and rebound check means coacting with said hammer to limit the movement thereof toward said support, said rebound check means comprising a checking element released for movement toward checking position when said hammer moves toward said support, said checking element being timed in its operation so as to be ineffective when said hammer is propelled at high speed by said propelling means, but effective upon slower rebound movements of said hammer.

47. Printing mechanism as described in claim 46, wherein said printing hammer is held in position of rest by said rebound check means at a distance from said support, and a carriage bearing a row of type members and movable to pass said type members through the space between said hammer and said support, said hammer being propelled past said rebound check means by said propelling means, to strike one of said type members, and being stopped by said rebound check means on a subsequent rebound movement, in position to clear the path of said type members.

48. In a printing mechanism, a frame having a guideway therein, a type member carriage having guide means thereon adapted to slide into and to reciprocate in said guideway, reciprocating drive means, and means detachably connecting said carriage to said reciprocating drive means, said carriage being free to slide wholly out of said guideway when said connecting means is detached.

49. In a printing mechanism, a type member, a carriage on which said type member is mounted for relative movement in one direction, means to move said carriage in a second direction perpendicular to said first direction, means to move said type member in said first direction as said carriage moves, and means to support a record sheet with a print receiving area parallel to said second direction, in position to be engaged by said type member when the latter is moved, said type member comprising a pivoted type-bearing head adapted to deflect on striking the sheet on said support.

50. In a machine of the class described, a printing mechanism including a member adapted to execute a movement to effect printing by the mechanism; a camming device, a feeler device, and spring means yieldably urging said feeler device into engagement with said camming device; and means controlling the start of the movement

of said member, including a normally disengaged coupling means, said coupling means being connected to said feeler device so as to be engaged, by movement of said feeler device into a receding portion of said camming device, and being actuated to initiate an operative movement of said member by the positive action of a following rising surface of said camming device.

51. In a printing mechanism, print control means comprising normally disengaged coupling means; a camming device, a feeler device, and spring means yieldably urging said feeler device into engagement with said camming device; said coupling means being associated with said feeler device so as to be coupled, by movement of said feeler device into a receding portion of said camming device, and to be moved to initiate a printing action by the positive action of a following rising portion of said camming device.

52. In a printing mechanism, a spring driven printing actuator, means to latch said printing actuator in retracted position, a coupling member normally disengaged from said latching means, a camming device, a follower device spring urged against said camming device, said coupling member being connected to said follower device so as to be coupled to said latching means by movement of said follower device into a low part of said camming device and to release said latching means as said follower device rides out of said low part of the camming device.

53. In a printing mechanism comprising a set of individually operable type members, a printing actuator adapted to operate any one of said type members, and means for presenting said type members to said printing actuator sequentially, print control means for controlling the time of operation of said printing actuator comprising normally disengaged movable coupling means, selecting means controlling the movement of said coupling means, a movable camming device having a plurality of mutually differentiated camming elements at spaced intervals thereon, said camming elements corresponding, respectively, to the different type members, said selecting means having parts to sense said camming elements successively as the camming device moves, each at the time the related type member is presented to said printing actuator, said parts being adjustable to conform to any one, and only one, of said camming elements, said selecting means being spring urged to execute a movement to cause the engagement of said coupling means, upon the sensing of conforming camming elements by said adjustable parts, and being cammed by said conforming camming elements to initiate an operation of said print control means.

54. In a printing mechanism, a printing actuator, spring operated propelling means therefor, a set of type members; means to move said type members in sequence past said printing actuator, means to latch said printing actuator in retracted position against the force of said propelling means, normally disengaged latch releasing means, selective control means for detecting the approach of any selected type member of said set to said printing actuator, said selective control means being adapted, on detecting a selected type member, first to engage said latch releasing means and then to operate the latter to release said latching means.

55. In a printing machine, printing mechanism comprising a plurality of individual printing devices operating, respectively, in different columns of a record sheet, selective control means for said

printing devices comprising a plurality of groups of permutation elements, one group for each printing device a corresponding number of groups of settable storage elements mounted in a movable frame, each group of storage elements being adapted to coact with a particular group of said permutation elements and each storage element being adapted, when set, to coact with a related permutation element of the corresponding group, means for causing simultaneous operation of said printing mechanism under control of said selective control means and setting of said storage elements, means for restoring said permutation elements to non-set position, and means for rocking said frame to transfer the settings of said storage elements to said permutation elements.

56. In a record controlled storage mechanism for storing data represented on control records by code designations placed in different index point positions, in accordance with any one of a plurality of predetermined different codes, a group of settable code elements, means for sensing the index point positions of a record, and setting means for said code elements controlled by said sensing means and including means rendered effective upon the sensing of a single code designation in any one of certain index point positions for setting certain single ones of said code elements, the single code element being different for each of said certain index point positions, said setting means also including means rendered effective upon the sensing of a single code designation in any one of a plurality of other index point positions for setting a combination of the said single code elements, the combination being different for each of said other index point positions.

57. A storage mechanism as described in claim 56, wherein said setting means comprises a group of toothed disks respectively coacting with said code elements, said disks being joined together and having teeth arranged so as to be engageable with their respective code elements singly and in various combinations.

58. In a printing machine for interpreting information from records, on which the characters comprising the information are represented by code designations variably positioned in different index point positions within each of a plurality of individual character areas of the record, in accordance with any one of a plurality of predetermined codes; individual means to sense the different character areas of the records; printing mechanism comprising a plurality of printing units respectively associated with said individual sensing means; means to control the units of said printing mechanism selectively, including translating mechanism comprising a plurality of groups of settable elements, one group for each of said individual sensing means, setting means adapted to coact with the settable elements in the different groups to set the elements in each group in any one of a variety of single or combinational settings each representative of a different character, and means controlled by said sensing means to determine the action of the setting means upon the several groups of settable elements in each operation of the machine, said setting means including means rendered effective in response to the sensing of single code designations in certain index point positions for setting corresponding single settable elements, said setting means also including means rendered effective in response to the sensing of single code designations in other

index point positions for setting combinations of said single settable elements.

59. A printing machine as described in claim 58, wherein said sensing means sense the different index point positions of the character areas at differential times during the machine operation, said groups of settable elements being normally out of the influence of said setting means and being brought to coact therewith each time 10 a code designation is sensed in the related character area, said setting means having similar assemblies of setting elements to coact with the respective groups of settable elements, each of said assemblies including setting elements presented in coacting position singly and in different combinations at the successive differential times.

60. A printing machine as described in claim 58, wherein said sensing means sense the different index point positions of the character areas at differential times during the machine operation, said groups of settable elements being normally out of the influence of said setting means and being brought to coact therewith each time 20 a code designation is sensed in the related character area, said setting means comprising a rotary member having teeth aligned with said settable elements and arranged so as to set single settable elements or combinations of settable elements in the respective groups, depending upon the differential timing of the sensing of one or more code designations in the related character area of the record.

61. In a translating device, a group of settable elements mounted side by side so as to be relatively slidable in a setting direction, cyclically moving setting means having setting elements thereon in different planes for coaction with different ones of said settable elements, said settable 35 elements being normally clear of said setting elements but being movable together for engagement with the related setting elements, means for differentially timing said engaging movement of said settable elements, in relation to the cyclical movement of said setting means, said setting elements being arranged so that said settable elements are set thereby singly or in various combinations, depending upon the differential time of said engaging movement, each of said settable elements being provided with a cam effective, during the setting of said element, to restore the unset ones of said settable elements to normal position.

62. In a translating device, a rockably mounted 55 stirrup having a cross pin, a group of individually settable elements having slots embracing said cross pin, cyclically moving setting means having setting elements thereon for coaction with related ones of said settable elements, said settable elements being normally out of the paths of their related setting elements, but being movable into the paths thereof by the rocking of said stirrup, said setting elements being positioned so as to slide said settable elements singly, or in various 60 combinations, in dependence upon the time of rocking of said stirrup in the cycle of movement of said setting means, spring means urging said settable elements toward engagement, means for latching said stirrup to hold said settable elements out of engagement, setting control means for unlatching said stirrup at said differential times in the cycle, the slot of each of said settable elements being shaped so as to cam said cross pin back, as the settable element is slid by a 65 related settable element to relatch said stirrup.

63. In a translating device, a rocking holder, a group of settable elements supported thereby, cyclically moving setting means having setting elements adapted to coact with related ones of said settable elements to set the latter, means biasing said rocking holder and settable elements toward the position for coaction of said settable elements with said setting elements, means to latch said holder and settable elements in non-coacting position, means to trip said latch at differential times during the cycle of movement of said setting means, said setting elements being positioned for different single or combinational coaction with said settable elements at the various differential times during the cycle of movement of said setting means, means to retain the individual settable elements in set position independently of movements of the other settable elements, and means to restore said rocking holder and the unset ones of said settable elements to latched position immediately as each setting coaction occurs, whereby repeated setting coactions may take place within a single cycle of movement of said setting means.

64. In a translating means, a group of individually settable code elements, means for setting said code elements singly and in various combinations, to represent different characters, and means to retain any set code element in said position independently of movements of other code elements, said setting means including cyclically operable means having different setting elements for the respective code elements, arranged to be potentially effective singly or in different combinations, at differential times during the cycle, and means to determine the differential time or times during the cycle at which said setting means is made operative to set said code elements.

65. Translating means as described in claim 64, wherein said setting elements are arranged on said cyclically operable means so that each of various combinational settings of said code elements can be made either by making said cyclically operable means operative to set said code elements at one differential time, or at a plurality of different differential times.

66. In a translating mechanism, a group of individually settable code elements mounted side by side, a rotary setting device having peripheral teeth in different planes to engage the different code elements, said setting device being normally positioned so that said code elements are clear of said teeth, said setting device having a plurality of groups of teeth, each group in a different segment thereof, the teeth in the different groups being positioned in different combinations of the planes pertaining to the respective code elements, said setting device having further single teeth in said planes, each at a different segment thereof, and means whereby said code elements and said setting device can be made to coact during the rotation of said setting device through one or more single segments thereof.

67. In a printing mechanism, a printing actuator, a set of type members, means to present said type members to said printing actuator in succession, spring propelling means for said printing actuator, means to latch said printing actuator in cocked position, settable selective control means for releasing said latching means at

any one of various times, to cause said printing actuator to strike a particular one of said type members, setting means for said selective control means, comprising a plurality of individually shiftable elements, said setting means being adapted to move as a whole to transfer a setting to said selective control means, and means positioned to be operated by any one of said shiftable elements which has been shifted to a setting position, for operating said latching means to latch said printing actuator.

68. In a printing mechanism, a printing actuator, a set of type members, means to present said type members to said printing actuator in succession, spring propelling means for said printing actuator, means for cocking said printing actuator against the force of said propelling means, means to latch said printing actuator in cocked position, settable selective control means for releasing said latching means at any one of various times, to cause said printing actuator to strike a particular one of said type members, setting means for said selective control means, comprising a plurality of individually shiftable elements, said setting means being adapted to move as a whole to transfer a setting to said selective control means, means positioned to be operated by any one of said shiftable elements which has been shifted to a setting position, for operating said latching means to latch said printing actuator, and means for operating said cocking means and moving said setting means in synchronism, so that said latching means is operated as the cocking operation is completed.

69. In a printing mechanism, a paper support, a type member carriage mounted to reciprocate parallel to the paper on said support, and a type member mounted on said carriage so as to be movable in a direction normal to the paper on said support, means to impel said type member toward the picker as said carriage reciprocates, said type member including a pivoted type-bearing head adapted to deflect in either direction on striking the paper during movement of the carriage in either direction.

70. In a printing mechanism, a paper support, a type member support movable parallel to the paper on said support, a type member mounted on said support so as to be movable in a direction perpendicular to the paper, and pivoted so as to be capable of deflecting in either direction on striking the paper, and means for impelling said type member toward the paper as said type member support moves in either direction.

71. In a printing machine for interpreting information represented on control records by code designations placed in different index point positions, in accordance with any one of a plurality of predetermined codes; printing mechanism, variably settable selective control means for said printing mechanism, analyzing means to sense the control records, and setting means for said selective control means controlled by said analyzing means and including a plurality of means respectively rendered effective upon the sensing of differently positioned code designations, to coact with said selective control means to produce the same setting thereof for different code designations.

ROBERT E. PARIS.
